UNITED STATES PATENT OFFICE.

WILLIAM J. FABIAN, OF EVANSTON, ILLINOIS.

CHECK-WRITING MACHINE.

1,248,096.

Specification of Letters Patent. Patented Nov. 27, 1917.

Application filed February 13, 1915. Serial No. 8,083.

To all whom it may concern:

Be it known that I, WILLIAM J. FABIAN, a citizen of the United States, and resident of Evanston, county of Cook, and State of Illinois, have invented certain new and useful Improvements in Check-Writing Machines, of which the following is a specification, and which are illustrated in the accompanying drawings, forming a part 10 thereof.

The invention relates to apparatus for writing amounts in both words and figures by the operation of a single set of keys, and for indicating the sum of the amounts so expressed. The object of the invention is to provide a machine which may be conveniently employed for writing checks or drafts and for showing the sum of the amounts of the checks or drafts written. The invention accordingly contemplates apparatus of the kind indicated and the association of the same with typewriting mechanism and totaling mechanism whereby to completely perform all of the operations of writing a 25 large number of checks or drafts, as in making up a pay roll or a set of drafts upon customers, extending over a given period of business, and of adding together the amounts of the whole or any partial number of the 30 checks or drafts so written.

In the accompanying drawings,

Figure 1 is a plan view of a check writing machine embodying the features of improvement provided by the invention.

Fig. 2 is a vertical longitudinal sectional view of the same, the plane of the section being indicated by the line 2-2 of Fig. 3,

Fig. 3 is a vertical transverse sectional view taken on the line 3-3 of Fig. 2,

Fig. 4 is a detail plan view with parts of the case and frame work shown in section and with the cover of the case and certain of the operative parts which are located next below the cover, removed,

Fig. 5, is a face view showing a form of type sectors which may be employed for printing numerical amounts in both words and figures,

Fig. 6 is a detail plan view similar to Fig. 4, but showing a different part of the machine,

Fig. 7, is a detail front elevation, partly in section showing parts which may be employed for printing the items of the several 55 checks or drafts upon a separate strip together with the mechanism for adding to-

gether the amounts of the several items, but with some parts omitted,

Fig. 8 is a side view of the apparatus shown in Fig. 7, some of the parts being 60 shown in section and others being omitted,

Fig. 9 is a detail plan view showing the typewriter carriage and parts associated therewith,

Fig. 10 is a detail front elevation showing 65 apparatus for communicating motion from parts of the word printing mechanism to the corresponding parts of the figure printing mechanism, the type sectors being shown in section,

Fig. 11 is a detail side elevation partly 70 in section showing a form of clutch which may be employed upon the apparatus,

Fig. 12 is a detail sectional view taken on the line 12-12 of Fig. 6, 75

Fig. 13 is a detail side elevation showing 80 a form of cam which may be employed for actuating the printing platen and parts associated therewith, the floor of the case and the several shafts being shown in section,

Fig. 14 is a detail side elevation of the 85 gear mechanism which is employed for moving the type sectors, the several shafts being shown in section and the plane of the section being indicated by the line 14-14, on Fig. 3,

Fig. 15 is a detail sectional view taken on the line 15-15 of Fig. 3, showing a cam and the parts associated therewith employed 90 for actuating the item printing and the totaling mechanism,

Fig. 16 shows the cam illustrated in Fig. 15, in front elevation, a locating element therefor being shown in section,

Figs. 17 and 18 are sectional views taken 95 on the lines 17-17 and 18-18, respectively, of Fig. 3,

Fig. 19 is similar to Fig. 8 but shows the parts omitted from said figure,

Fig. 20 is a plan view showing checks of 100 the form which may be written by the apparatus connected together in a strip,

Figs. 21 and 22, are detail side views of 105 the gear sectors which may be employed for transmitting motion to the item printing and totaling mechanism, and

Fig. 23 is a detail sectional view of the key board.

The drawings are intended to merely illustrate one way in which the several features 110 of the invention may be embodied in an operative machine. As shown, this machine

is adapted for writing checks, as 50, 51, (Fig. 20), which are connected together in the form of a continuous strip; for printing the items of the several checks upon another strip, as 52 (Fig. 2), hereafter referred to as the stub record strip; and for showing the total of the amounts of all or any partial number of the checks, either visually, as through a sight opening in the machine case, or by printing the same, when desired, upon the stub record strip 52. For this purpose the machine preferably includes a form of typewriter mechanism adapted to print any desired written matter, as the name of the payee, indicated at 53, (Fig. 20). It also includes apparatus for printing the amount of a sum of money, in both words and figures, as indicated at 54 and 55, respectively. The items and totals are printed upon the stub record strip 52, in figures only.

The mechanism for printing any written matter upon the check, as the name of the payee indicated at 53 (Fig. 20) is operated from a key board generally designated 56 and shown in Figs. 1 and 2. This key board comprises a plurality of spring elevated key levers, one of which is shown in detail at 57 (Fig. 9). The mechanism for printing the amount of the check in both words and figures is operated from a key board which is generally designated 58, and comprises a plurality of plunger keys, as 71.

The several mechanisms are principally inclosed within a case, generally designated 59, the key boards 56 and 58 both appearing upon the top of the case adjacent its forward end. The totaling mechanism is preferably arranged to show a visible total through a sight opening, as 60. The sight opening is conveniently provided in a panel, as 61, of the top wall of the case at one side of the key board 58. In addition to the panel 61, the top of the case includes a hinged panel or cover 80. The floor of the case is marked 65. The numbers 64, 88 and 89 indicate the front and the two side walls of the case, respectively. The rear wall 90 of the case extends to and has hinged connection with the cover panel 80, at 91. Side frames 92, 93, rising from the floor 65, within the chamber of the case, provide the principal supporting means for the operating parts.

The stub record strip 52 turns over a platen roller 62 which is exposed through an opening 63 in the front wall 64. The strip upon which the checks, as 50, 51, are written, enters and is delivered through slotted openings 66, 67, (Fig. 2) in the floor 65. Between the slotted openings 66 and 67, the strip passes through guide tubes indicated at 68 and 69, and turns about a platen roller 70. The guide tubes 68 and 69 are carried by and rise from the floor 65 in such

manner as to cover the openings 66 and 67, respectively. The printing of the name and the amount upon each check are accomplished by swinging the platen roller 70 in opposite directions against the type characters of the typewriter mechanism and the amount writing mechanism, hereinafter described.

Most desirably the several mechanisms of the machine are principally actuated by power. For this purpose a driving gear 72 (Fig. 2) is continuously turned by a motor (not shown). To afford convenient connection with the motor, the driving gear 72 may be partially exposed upon the under side of the case 59. As shown, it is journaled in brackets, as 73, which are secured against the under side of the floor 65, and only one of which appears in the drawings. A part of the driving gear 72 projects into the chamber of the case through an opening 74 in the floor 65. A gear 75 within the chamber of the case 59 meshes with the gear 22 and is continuously driven thereby. The gear 75 normally turns loosely upon a shaft 76 which is journaled in and extends between the side frame 92, 93. The shaft 76 is normally stationary but a clutch arm 77 is fixed thereon at one side of the gear 75. The clutch arm 77 carries a pawl 78 and this pawl is adapted to be spring advanced into the path of a series of studs 79 formed upon the adjacent side face of the gear 75, for operatively connecting the gear 75 and shaft 76.

100

The typewriter mechanism.

The key levers 57 (Fig. 2) extend rearwardly beneath the hinged panel 80 of the top wall or cover of the case 59. As shown, each lever is pivotally secured to a lug, as 81, which depends from the under side of the panel 80. At its forward edge the panel 80 is provided with an inturned flange 82 having slotted openings, as 94, through which the key levers 57 extend.

It is desirable that in lieu of separately printing each letter or figure of the matter to be written, as the name of the payee indicated at 52, Fig. 20, the entire matter to be written is first to be set up from type characters, as 95, arranged in a line, and this line of type characters is then to be printed at a single operation. As shown, the type characters 95 are fixed upon the rims of a set of wheel segments 83, Fig. 2. The number of wheel segments 83 preferably equals the number of individual letters and spaces which may be contained in the line of writing to be produced and each segment carries an entire set of the type characters 95. The printing of any desired matter is provided for by rotating the several wheel segments 83 through the proper distance to align the corresponding type characters in 130

front of the platen 70, Fig. 2. For this purpose, a single actuating arm 84 may be employed. In that event, the arm 84, extends continuously beneath the rims of all of the 5 wheel segments 83 and the distance through which each wheel segment is turned by said arm is determined by providing each set of wheel segments with a series of movable studs 85, any one of which may be depressed 10 into the path of the arm.

The selective depression of the movable studs 85 of the several wheel segments 83 is accomplished by the coaction of the key levers 57 and a traveling communicator carriage, generally designated 86. In order 15 that each of the key levers 57 may coact with the corresponding part of the communicator carriage 86 in any position of the latter, each of the key levers 57 is provided with a 20 transverse arm 87 (Fig. 9) covering the entire travel of the carriage 86.

The communicator carriage 86 travels upon a pair of stationary rods 96, 97, as ways or rails. These rods extend between and are 25 supported upon the side frames 92 and 93. If desired, the carriage 86 may be provided with rollers, as 98, at each end for engagement with the corresponding rod, 96, 97.

For its travel in one direction the communicator carriage 86 is preferably actuated 30 by a spring drum 99 of a form which is well known from its use in actuating the traveling carriage of typewriters. The drum 99 is mounted in a convenient position upon a 35 fixed part of the machine, as the side frame 92. A metallic ribbon 100 which winds upon the drum 99 in a well known manner, connects with the communicator carriage 86.

The movement of the communicator carriage 40 86 is controlled by an escapement mechanism generally designated 101. This escapement mechanism includes a fixed ratchet bar 103, the ratchet teeth 102 being formed along the upper edge of the bar. The bar 45 103 extends horizontally between and is secured to the side frames 92 and 93. An arm 104 is fixed to the carriage 86 and extends rearwardly therefrom over the bar 103. This arm carries a sliding sleeve 105 and a 50 spring pawl 106 is mounted against the under-side of the sleeve 105, for coöperating with the ratchet teeth 102. A fixed stop 107 formed on the sleeve 105 limits the movement of the pawl 106 in one direction. A 55 spring or yielding stop 108 carried by the sleeve 105 limits that movement of the pawl 106 in the other direction which is imparted to the pawl by the pressure of its own spring (not shown).

60 A stud 109 rigidly mounted on the sleeve 105 also coöperates with the ratchet teeth 102 for controlling the movement of the communicator carriage 86. This stop is so positioned with reference to the pawl 106 that a 65 sliding movement of the sleeve 105 on the

arm 104, in one direction, carries the pawl 106 out of engagement with the ratchet teeth 102, and brings the stud 109 into engagement with the same ratchet tooth from which the pawl is withdrawn. The pawl is then thrown 70 against the yielding stop 108 by its spring (not shown). A return movement of the sleeve 105 on the arm 104 brings the pawl 106 into engagement with the next ratchet tooth 102 and the yielding of the pawl toward the fixed stop 107 permits the spring drum 99 to effect a corresponding advance movement of the carriage. The yielding of the stop 108 permits the pawl 106 to slide over the ratchet teeth 102 during movement 80 of the communicator carriage 86 in the opposite direction.

The sleeve 105 is reciprocated upon the arm 104 at each operation of any one of the key levers 57. In order that the mechanism 85 for effecting this reciprocation of the sleeve may be operable in any position of the communicator carriage 86, it acts upon the sleeve 105 through a bar 110, which extends from side to side of the machine frame. 90

This bar has a slotted opening 111 and a stud 112 carried by the sleeve 105 travels in the slot. The bar 110 has its opposite ends slidingly connected with the side frames 92 and 93, respectively, as by set screws 113, 95 each of which extends through a slotted opening 114, in the bar. The bar 110 is shifted by the depression of any one of the key levers 57, through a pair of links 115, 116, which extend forwardly from the bar 100 and are connected at their forward ends, by a rod 117.

The rod 117 extends transversely beneath all of the key levers 57. It is moved rearwardly upon the depression of any one of the key levers by a cam engagement of the key levers with the rod. The forward ends of the links 115, 116 and the rod 117 are guided in their movements by means of a pair of guide links 118, 119. Each of these 110 guide links has one end pivotally connected with the rod 117 and the other end pivotally connected with a fixed support, as the rod 96. A spring 120 (Fig. 2) reacts between one 115 of the said guide links, as 119, and the adjacent side frame 93 to return the rod 117 after it has been moved rearwardly by the depression of one of the key levers 57 to accomplish the forward movement of the sleeve 105. 120

The return movement of the communicator carriage 86 will usually be accomplished by power, as from the shaft 76. As shown, a grooved cam 121 (Fig. 6) is fixed upon the shaft 76 for this purpose. For communicating motion from this cam to the carriage, a rock shaft 122 is pivotally secured against the floor 65 of the case 59 and carries two crank arms, designated 123 and 124 respectively. The crank arm 123 carries a stud 130

125 which runs in the groove of the cam 121. The other crank arm 124 is connected with a sliding pusher 127, as by a link 126. This pusher runs upon the bar 103, as by being provided with pins 128 which extend through a slotted opening 129 in the bar. A stud 130, mounted on the pusher 127, extends into the path of a depending part 109 of the sleeve 105. Rotation of the shaft 76 through one complete revolution accordingly moves the pusher 127 to and fro on the bar 103, the stud 130 coming into contact with a depending part 109, of the sleeve 105, in its movement and effecting a return movement of the communicator carriage 86 from any intermediate position or the full travel position which the communicator carriage may have occupied.

In some instances, as when an error has been made in the depression of the key levers 57, it may be desired to return the communicator carriage 86 by hand. For this purpose the arm 104 is extended through a slotted opening 132 in the cover panel 80, to a conveniently accessible position (Fig. 1).

The communicator carriage 86 is supplied with movable communicator plungers 133, the number of these plungers being equal to the number of key levers 57, or studs 85, and the number of key levers 57 and studs 85 being each equal to the number of type characters 95 in any set. The plungers 133 operate vertically through the communicator carriage 86 and each is normally held in an elevated position by a spring 134. As shown, the plungers 133 have stems 135 of reduced diameter and that part of the carriage 86 through which the plungers operate is composed of a pair of vertically separated rails 136, 137. The springs 134 are coiled about the stems 135 of the plungers 133 between the rails 136, 137, and react between the lower rail, as 136, and the enlarged head, as 138, of the corresponding plunger.

Depression of any one of the key levers 57 accordingly causes its transverse arm 87 to engage and depress the corresponding communicator plunger 133 in any position of the communicator carriage 86. The depression of one of the communicator plungers 133 in turn serves to depress the corresponding stud 85 in the particular one of the wheel segments 83 with which the communicator carriage is, at the time, alined. It will be understood that the key-board 56 includes, in addition to the key levers 57, a space bar 139 carried by levers, as 140, like the key levers 57, but without the transverse arm 87 and operable only upon the rod 117.

The alinement of the type characters 95 in front of the platen 70, in accordance with the operation of the key levers 57 and space bar 139 of the key board 56, is accomplished by a swinging movement of the arm 84 to the right, as viewed in Fig. 2. If the aline-

ment of the type characters is to be merely for the purpose of showing whether or not the key board 56 has been correctly used to obtain the desired selection of type characters, the swinging of the arm 84 is preferably accomplished by hand. If, on the other hand, the alinement of type characters is for the purpose of printing the desired matter, as the name 53 on the check 50 (Fig. 20), the arm 84 is desirably moved by power. In either case the arm 84 engages those studs 85 which have been depressed and alines them against a fixed stop arm 141. On the return movement of the arm 84 the type characters 95 are returned to their original positions. This is accomplished by the engagement of the arm 84 with a spoke, as 142, of each of the wheel segments 83. The fixed stop arm is connected to the side frames 92, 93, at its opposite ends and extends through the wheel segments 83.

The swinging movement of the arm 84 by hand is accomplished by rotating a shaft 143. This shaft also serves for supporting the several wheel segments 83, but the wheel segments are loosely pivoted upon the shaft to permit the shaft to rotate independently of the wheel segments. As shown, the shaft 143 extends from side to side of the machine, and is journaled in the side frames 92 and 93. A pair of cranks 144 (Fig. 12) and 145 (Fig. 2) are pivoted upon the shaft 143 adjacent its opposite ends, and carry the arm 84.

In the power movement of the arm 84 the cranks 144 and 145 turn independently of the shaft 143. This movement of the arm is conveniently accomplished through a plate cam 146. The cam 146 is fixed upon the shaft 76. A link 147 serves for communicating motion from the cam 146 to the crank 145. As shown, the link 147 is supplied with a roller 148 at its lower end, and this roller runs in a cam groove 149 (Fig. 2) which is formed in one of the side faces of the plate cam 146. A second link 150 is employed for guiding the movement of the lower end of the link 147. The link 150 is pivotally connected with the lower end of the link 147 at one end. The other end of the link 150 is pivotally mounted upon a tie rod 151 (Figs. 1 and 6) of the machine frame. The higher end of the link 147 is operatively connected with a crank arm 152 which is formed integral with the crank arm 145 (Fig. 6). To permit the crank arm 152 to swing without movement of the link 147, as when the type characters 95 are to be alined for examination, the higher end portion of the link 147 is formed with a slotted opening 153. The upper end of this slotted opening is rearwardly offset, as at 154 (Fig. 2). A stud 155, fixed in the crank arm 152, enters the slotted opening 153. Normally the stud 155 is engaged with the rearwardly offset portion 154 of this slotted opening. Under 130

these circumstances, the vertical reciprocation of the link 147, effected by the cam 146, serves to impart the required movement to the arm 84 in both directions. Preferably 5 the cam groove 149 (Fig. 2) is so shaped as to obtain the complete movement of the arm 84 in one direction, during the first quarter revolution of the plate cam 146, after which the arm 84 is held stationary during a half 10 revolution of the cam. The return movement of the arm 84 is completely accomplished during the last quarter revolution of the cam.

A crank arm 156 (Figs. 1, 6 and 12) preferably exposed upon the outside of the case 59, serves for moving the arm 84, by hand. As shown, this crank arm is mounted upon a short shaft 157. This shaft is journaled in the side frame 92 (Fig. 12), above the 20 shaft 143, and extends through an opening 158 in the side wall 88 of the case, for receiving said crank. A pinion 159 is fixed upon the inner end of the shaft 157 and meshes with a pinion 160 which is fixed upon the 25 shaft 143.

For communicating motion from the shaft 143 to the arm 84, the hub, as 161, of the crank arm 144 and the hub 162 of the pinion 160 are located side by side upon the shaft 30 143 and a stud 163 projects laterally from the former into an elongated recess 164, formed in the latter. The normal position of the stud 163 in the elongated recess 164 is such that during the initial movement of 35 the shaft 143 by hand, the shaft 143 turns without moving the cranks 144, 145 and 152 and that during the movement of the cranks 144, 145 and 152 by power, these cranks move without turning the shaft. A spring 165, 40 (Fig. 12) is preferably provided to insure a return of the parts to a normal position after each operation of the crank 156. As shown, this spring is coiled about the shaft 157 and reacts between the crank arm 156 and the 45 side frame 92. A stud 166, formed upon a hub 167, which is fixed upon the shaft 143 adjacent to but independently of the crank arms 145 and 152, serves to engage the link 147 and move the latter rearwardly by a cam 50 action upon the initial movement of the shaft 143 by hand, to disengage the stud 155 from the rearwardly offset portion 154 of the slotted opening 153, before the crank arm 152 begins to move with the shaft.

55 The studs 85 which have been depressed by the operation of the key levers 57 are most conveniently returned when alined against the stop arm 141. If this alinement of the studs has been manually accomplished by the use of the hand crank 156, the studs will only be returned in event it is found that an error has been made in the use of the keyboard 56. In this case, the return of the studs is preferably accomplished 60 by hand. For this purpose an erasing key

168 (Fig. 1) is preferably provided. As shown, this key is exposed upon top of the case 59 at one side of the key board 56. It slides through the panel 61 of the top wall of the case and is connected at its lower end 70 with a lever 169, (Fig. 2). The lever 169 is fulcrumed on the side frame 93, as at 170. Depression of the erasing key 168 serves to lift a restoring bar 171 which extends beneath the studs 85 when alined against the 75 stop arm 141. The restoring bar 171 is supported at its opposite ends by short cranks 172, each of which is pivotally mounted upon the corresponding side frame 92, 93, as at 173, but only one of which is shown. A link 80 174 is connected with one of the cranks 172 and extends downwardly therefrom. A stud 175 is fixed in the link 174 intermediate its ends and projects over the adjacent end of the lever 169 to provide for the elevation of 85 the restoring bar 171 by the depression of the erasing key 168.

In the normal operation of the machine the link 174 is actuated by power to raise the restoring bar 171 after printing has been 90 accomplished from the selected type characters 95 by a movement of the platen toward the wheel segments 83. For this purpose the lower end of the link 174 is engaged with the plate cam 146, as by being provided with an antifriction roller 176 which rides upon the rim of the cam. A projection 177 formed on the rim of the plate cam 146 serves to engage the roller 176 for raising the link 174 and the restoring bar 171 100 at a predetermined time in the rotation of the shaft 76. As shown, the projection 177 is so positioned on the plate cam 146 that the restoration of the studs 85 is accomplished just before the return movement of 105 the arm 84, by the cam groove 149, is begun. The link 174 is guidedly supported adjacent its lower end in any convenient manner as by means of a swinging link 178 which has one end connected with the link 174, and the other end pivotally mounted upon the tie rod 151.

The arrangement of the type characters 95 in accordance with operations of the key levers 57 and space bar 139 of the key board 115 56 is visibly displayed through a slotted sight opening 179 in the cover panel 61 of the case 59. For this purpose a plurality of sets of intermeshing gears 180, 181, 182 and 183, equal in number to the number of 120 wheel segments 83, but only one set of which is shown, are provided. All of these gears are rotatably mounted upon tie rods 184, 185 and 186 which extend between and are supported upon the side frames 92 and 93. 125 The teeth of the gear 180 engage notches 187 formed in the rim of the corresponding wheel segment 83 and some of which are located between adjacent type characters 95. The gear 181 is fixed against the gear 180 130

- to rotate therewith and the rotation of these gears in accordance with the selective rotation of the corresponding wheel segment 83 is communicated to the gear 183 through 5 the intermediate gear 182. The gear 183 is located adjacent the sight opening 179. For the purpose of indicating the position of the corresponding wheel segment 83, a letter wheel 183^a, having suitable characters (not 10 shown), of the same kind, and arranged in the same order as the type characters 95, provided upon its rim, is secured against each of the gears 183, and rotates therewith.

An examination of the characters displayed upon the letter wheels 183^a through the sight opening 179 (Fig. 2), after the wheel segments 83 have been moved by the actuating arm 84 in accordance with the operation of the key levers 57 and space bar 20 139 of the key board 56, serves to show whether the said key levers and space bar have been correctly operated to produce the desired written matter, as the name 53 (Fig. 20) upon the check, as 50. In event the 25 movement of the actuating arm 84 has been accomplished by hand, through the use of the crank 156, and it is found that an error has been committed in the use of the key board 56, the erasing key 168 (Figs. 1 and 2) will be operated before the crank 156 is 30 released, thereby elevating the restoring bar 171 against those studs 85 which have been depressed while the studs are alined against the stop arm 141. The hand crank 156 may 35 be then released and if the end of the arm 104 which projects through the slotted opening 132 of the hinged cover panel 20 (Figs. 1 and 2) be used for restoring the communicator carriage 86, to its original position, 40 the use of the key board 56 may be repeated for the purpose of obtaining a correct alignment of the type characters.

The amount writing mechanism.

- 45 The types for printing the amount of the check in both words, as 54, and figures, as 55 (Fig. 20) may be arranged in accordance with the plan illustrated in Fig. 5. As shown, these types are principally mounted 50 upon the rims of a plurality of wheel segments generally indicated by the numerals 188 to 201 inclusive. In the machine which is here used as an illustration, provision is made for printing amounts including the 55 first two decimals and any number of dollars up to 9,999. In this case there are fourteen of the said wheel segments. Five of the wheel segments, as those designated 188, 189, 190, 191 and 192 are arranged for 60 printing the number of dollars in words. Each of these wheel segments accordingly has a relatively wide type bearing rim, as 202, and the same is supported against the edges of a pair of plates or disks, as 203 and 204. The wheel segments designated

by the numerals 193 to 201 inclusive, are only used for printing figures. Each of these last mentioned wheel segments accordingly includes a relatively narrow type bearing rim, as 205, and this rim is mounted 70 upon the edge of a single plate or disk 206.

All of the wheel segments, 188 to 201 inclusive, are rotatably mounted in alignment upon a shaft 207 (Figs. 2 and 3) with the type bearing rims, as 202 and 205, facing 75 the platen roller 70. In order that the shaft 207 may support the several wheel segments for printing, it is preferably of stout construction. As shown, it extends between, and has its ends rigidly fixed in, 80 the side frames 92 and 93. In arranging the types for printing any desired amount in both words and figures the several wheel segments are rotated through selected variable angular distances. This selection of 85 the angular distances through which the wheel segments are to be rotated is accomplished by the use of the key board 58.

The keyboard 58 includes a plurality of sets of keys generally designated by the numerals 208 to 214 inclusive, the same being equal in number to the number of figures in the amount containing the greatest number of figures which may be written. There are also two additional sets of keys 90 generally designated 215 and 216, respectively. The keys of these two last mentioned sets are respectively operated only when the amounts to be written include a number of dollars, or a number of thousands of dollars, extending between eleven and nineteen inclusive. The use of these two additional sets of keys arises from the fact that the word "ten" is not used as the initial part of the names of the numbers from eleven to 100 nineteen but the first syllables of the names of all of these numbers are different. Similarly, a number of type characters for printing the syllable "teen" must appear on each of the wheel segments 188 and 191 in order 110 that one of these type characters may correspond in position with the type character for printing each of the numbers 3, 4, 5, 6, 7, 8, and 9 on the wheel segments 195 or 198 (Fig. 5). 115

All of the keys of the key board 58 are spring elevated and preferably take the form of vertically movable plungers having stems, as 217 (Fig. 3), with the elevating spring, as 235, coiled about the stem. 120 The stems 217 of the keys slide through the cover panel 61 of the case 59, and through a plate 218 within the case. The plate 218 is supported below and spaced apart from the cover panel 61, as by flanges 125 219 and 220 which depend from the said cover panel. The stems of the keys are operable upon movable studs, 232, 233 (Fig. 3) carried by those wheel segments which are designated by the numbers 188 to 194 in- 130

clusive (Fig. 5). The positioning of these studs determines the amount of angular movement to be imparted to the wheel segments by which they are respectively carried. Each of the wheel segments designated by the numbers 195 to 201 inclusive has movement transmitted to it from the corresponding segment 188 to 194. The wheel segments 195 to 201 are accordingly not provided with movable studs. The studs 232 are carried by the wheel segments 188, 189, 190, 191 and 192 having the relatively wide type bearing rims 202. These studs are accordingly bifurcated, their separated legs 360, 361 (Fig. 3) sliding through the rim of the corresponding wheel segment adjacent its opposite edges. The studs 233 are carried by the wheel segments 193 and 194 and slide centrally through the rim of the corresponding wheel segment.

In order that the keys may be compactly arranged in the key board 58 while still permitting the stems 217 to coöperate with the proper studs 232, 233, the stems 217 of some of the keys 209, 210, 211, 212, 213 and 214, have offset portions 221 intermediate their ends, most clearly shown in Figs. 2 and 3. The keys of the two sets which are designated 215 and 216, on Fig. 1, are each operable upon the studs 232 of a pair of adjacent wheel segments, as 188 and 189, or 191 and 192. To this end the stems 217 of the keys of these sets are bifurcated as indicated at 222 (Fig. 2), the two elements, as 223 and 224, of the bifurcated part of each stem, as the stem of either one of the keys marked 15 (Fig. 1), being offset and operable through the plate 218 in alinement respectively with the studs 232 of the wheel segments 189 or 192, which corresponds with the type character "fif" (Fig. 5), and which the stud 232 of the wheel segment 188 or 191 which corresponds with the type character "teen" alined with the type character "5" on the wheel segment 195 or 198.

Each of the wheel segments 188, 189, 190, 191 and 192 is desirably provided with type 230 (Fig. 5) constructed to print stars, or other characters for filling a blank, when no words are to be printed therefrom. Similarly, the wheel segments 193 and 194 are each provided with type 231 constructed to print a cipher when no numerals are to be printed in the columns to which these segments respectively relate. Preferably the type 230 and 231 are so arranged upon the corresponding wheel segments as to be presented to the platen 70 without movement of the segments. Each of the several wheel segments 188 to 194 inclusive is accordingly only required to be provided with a number of studs 232 or 233 which is equal to the number of characters other than the stars 230 or cipher 231 to be printed from the corresponding segment. The wheel seg-

ments 190, 193 and 194 each have nine additional type characters, as 234 and 235. These segments therefore each require only nine of the studs 232 or 233. These nine type characters 234 or 235 and studs 232 or 233, respectively correspond with the number of keys in the sets which are generally designated 210, 213 and 214 on Fig. 1.

Each of the wheel segments 188 and 191 has nine word type characters 236, constructed to print the words one to nine inclusive, and in addition nine other type characters 237, which, in conjunction with nine type characters 238 on the adjacent wheel segment 189 or 192, serve for printing the words eleven to nineteen inclusive. The wheel segments 189 and 192, also, each have nine additional type characters 239 constructed to print the words representing the amounts ten to ninety inclusive, by tens. It follows that each of the wheel segments 188 189, 191 and 192 are to be provided with eighteen of the studs 232. Nine of the studs 232 of each of the wheel segments 188, and 191 corresponding with the nine type characters 236, are controlled by the single stems 217 of the several keys of the corresponding set 208, or 210. Similarly nine of the studs 232 of each of the wheel segments 189 and 192, corresponding with the nine type characters 239 are controlled by the single stems of the several keys of the corresponding set 209 or 212. The remaining nine plungers of each of the wheel segments, 188 and 189, corresponding with the type characters 237 and 238, respectively are controlled in pairs, including one plunger of each wheel segment, by the two elements 223 and 224 of the bifurcated stems of the several keys of the set designated 215. Similarly the remaining studs 232 of the wheel segments 191 and 192 are controlled in pairs comprising one plunger of each wheel segment by the two elements 223 and 224 of the bifurcated stems of the keys of the set designated 216.

The wheel segments designated 188 to 194 inclusive are successively moved in accordance with the setting of the studs 232, 233 by the repeated oscillations of a swinging actuating arm 240, hereafter referred to as the driver, and the direct engagement of this driver with the said studs of the several segments in turn. Each of the wheel segments 195 to 201 is moved with the corresponding one of the segments 188 to 194 through being, at the time, connected therewith by a movable follower arm 261, hereinafter referred to as the transmitter. It is accordingly desirable that some type characters be repeated on certain of the wheel segments 195 to 201. The numeral characters designated 241, each appear twice on each of the wheel segments 195 and 198 for the reason that each of these characters appears both in the numbers one to nine and 130

- in the numbers eleven to nineteen, and is used in connection with different words in the two instances. Similarly the type character 242, used for printing the figure "1" 5 appears ten times on each of the wheel segments 196 and 199 for the reason that it appears in each of the numbers ten to nineteen inclusive and is used in connection with a different word in each instance.
- 10 The driver 240 is supported in two cranks 244 and 245, both of which swing upon the shaft 207. It engages the studs 232 or 233 of the wheel segments 188 to 194, successively, beginning at the right, as viewed in 15 Fig. 3. When there are seven of these wheel segments, as shown, seven oscillations of the driver 240 are required to move all of the segments. The separate engagement of the driver with the studs 232, 233 of the several 20 wheel segments is accomplished by providing the driver 240 with a plurality of spurs 243. These spurs are so spaced as to be alined with the studs 232 or 233 of only one wheel segment in any position which the 25 driver assumes. The spacing of the spurs 243 is further arranged to provide that these spurs are brought successively into alinement with the studs 232, 233 of the several wheel segments by a uniform longitudinal 30 step by step movement of the driver. These longitudinal movements of the driver occur after each complete oscillation, except the last.

For permitting the required movements of the driver 240, it is slidingly engaged with the crank 245, and this crank is, in turn, fixed against longitudinal movement on the shaft 207. The crank 244 is fixedly connected with the driver and has a longitudinal sliding movement on the shaft 207. The two movements of the driver 240 are accordingly accomplished by swinging the crank 245 and moving the crank 244 along the shaft 207. These movements are repeated 45 the required number of times by being derived from a shaft 247 which has seven revolutions at each operation of the machine. A cam plate 246, mounted on the shaft 247, serves for swinging the crank 245. The 50 shaft 247 extends between and is journaled at its opposite ends in the side frames 92, 93, as most clearly shown in Fig. 3. The cam plate 246 operates upon the crank 245 through an intermediate crank 248. The 55 crank 248 is pivotally supported upon a tie rod 249 of the machine frame and carries a cam roller 250. This cam roller runs in a cam groove 251 formed in a side face of the cam plate 246. A link 252 serves for connecting the intermediate crank 248 with an integral arm 253 of the crank 245.

A screw shaft 254 is employed for moving the crank 244 along the shaft 207 to shift the driver 240 after each complete oscillation of the crank 245. As shown, the screw

shaft 254 is fixed to the crank 244 at 258 and extends outwardly therefrom. This screw shaft has a pair of separated fixed sliding supports 255 and 256. The supports may be provided in any convenient manner as by 70 being formed upon a bracket arm 257. As shown, this bracket arm is secured against and projects inwardly from the side frame 93. A geared nut 259 runs on the screw shaft 254 between the supports 255 and 256. 75 The longitudinal movement of the screw shaft 254 and the accompanying shifting of the driver 240 is accomplished by a repeated rotation of the nut 259 at predetermined intervals. For this purpose a gear segment 80 260 is fixed upon the shaft 247, and intermittently engages the geared nut 259 during the seven successive revolutions of the shaft. The transmitter 261 is most clearly shown in Fig. 10. It is mounted in cranks 85 262 and 263 in the same manner that the actuating arm 240 is mounted in the cranks 244 and 245, respectively. Furthermore, the cranks 262 and 263, like the cranks 244 and 245, are swingingly mounted upon the shaft 90 207, the crank 262 being fixed against longitudinal movement thereon and the crank 263 being slidable on the shaft.

Each of the wheel segments 188 to 194 inclusive has a forwardly facing instanding 95 rigid stud 264 for engagement with spurs, as 267 of the transmitter 261. Whenever one of the wheel segments 188 to 194 is moved through a selected angular distance, the transmitter 261 is accordingly moved 100 through a like distance. For communicating this movement to the wheel segments 195 to 201 a rearwardly facing yielding pawl 265 (Fig. 2) is mounted upon each of the last mentioned wheel segments. These pawls 105 are successively engaged by a single spur 266 formed upon the transmitter. Furthermore, the spurs 267 are so positioned on the transmitter as to cause it to be successively engaged with the wheel segments 188 to 194, 110 beginning at the right, as viewed in Fig. 10. In the position shown in Fig. 10, one of the spurs 267 is engaged with the forwardly facing rigid stud 264 of the wheel segment 193 and the single spur 266 is in alinement 115 with the rearwardly facing yielding pawl 265 of the wheel segment 200. Upon the next movement of the transmitter 261 to the left, as viewed in Fig. 10, one of the spurs 267 will register with the stud 264 120 of the wheel segment 194 and the spur 266 will come into alinement with the yielding pawl 265 of the wheel segment 201.

The longitudinal movements of the transmitter preferably occur after each forward 125 movement of the same and before its return movement. This shifting is accomplished by a mechanism similar to that employed for shifting the driver 240. As shown, a screw shaft 268 is fixedly attached to the crank 130

263, at 269, and extends outwardly therefrom along side of the screw shaft 254. It slides through the same fixed supports 255, 256, which are provided for the screw shaft 5 254. A geared nut 270 runs on the screw shaft 268 between these supports. This nut is intermittently engaged by a gear segment 271, fixed upon the shaft 247. The positioning of the gear segments 260 and 271 10 on the shaft 247, with reference to the form of the cam 246, provides for the longitudinally shifting of the driver 240, after each complete oscillation of the crank 245, and for the shifting of the transmitter 261 after 15 each forward movement of the crank 245, but before its return movement. The return movements of the transmitter 261 are accomplished by the return movements of the crank arm 245. For this purpose a lug 272 20 is formed upon the hub, as 273, of the crank 245 and enters an angularly elongated recess 274 provided in the hub, as 275, of the crank 262.

The return movements of the driver 240 25 and transmitter 261, in the direction of their length, are accomplished by reversely driving the geared nuts 259 and 270. This is accomplished by the engagement of the geared nuts with a segmental gear 276 (Figs. 3 and 30 14), which is loosely mounted on the shaft 247. The segmental gear 276 is driven at intervals, as from a shaft 277, Fig. 3, which extends between and is journaled in the side frames 92, 93, below the shaft 247. As 35 shown, a pinion 278 is rigidly connected with the segmental gear 276 and this pinion is engaged at intervals by a gear segment 279 which is fixed upon the shaft 277. If desired, a Geneva stop mechanism may be 40 employed for holding the gear 276 and pinion 278 against rotation except when the pinion is engaged with the gear segment 279. As shown, the shoe 280 of this Geneva stop mechanism is carried by the pinion 278 and 45 the mutilated disk 281, for engagement with the shoe, is mounted upon the shaft 277 adjacent the gear segment 279 and rotates therewith. Similarly Geneva stop mechanisms may be employed for holding the 50 geared nuts 259 and 270 against movement except when the same are to be rotated. As shown, the shoe elements 282 and 283 of these mechanisms are formed upon the geared nuts 259 and 270 respectively. These 55 shoes are respectively engaged with the curved rims of disk segments 284 and 285 which are mounted upon the shaft 247 and rotate therewith.

Provision for printing the check with 60 the appropriate one of the words "cents" or "dollars" is preferably provided. As most clearly shown in Fig. 5, the type characters 286 and 287 for printing these words are formed upon a movable plate 288. This 65 plate is conveniently supported in front of

the platen 70 by being mounted upon the outer end of a crank arm 289 (Fig. 2) which extends outwardly from and is journaled on the shaft 207 between the wheel segments 193 and 199. Similarly movable 70 plates 290 and 291 bearing the type characters 292 and 293 for printing the words "hundred" and "thousand" are located between the wheel segments 189 and 190 and 190 and 191, respectively. These two last mentioned movable plates are mounted upon crank arms, as 294 and 295. The crank arm 294, like the crank arm 289 extends outwardly from and is journaled upon the shaft 207. To provide room for other parts 80 the crank arm 295 (Fig. 3) is preferably shorter than the crank arms 289 and 294. As shown it is pivotally mounted upon the higher end of a post 370 which rises from the tie rod 249. 85

The movable plate 288 is normally so positioned as to present the type character 286 for printing the word "cents" to the platen 70. Its position is shifted to present the type character 287 for printing the word "dollars" to the platen whenever any wheel segment to the right (Fig. 5) is moved. Similarly the movable plates 290 and 291 are normally so positioned as to present type characters 296 and 297 for 90 filling a blank, as by printing stars, to the platen 70. The plate 290 is shifted to present the type character 292 for printing the word "hundred" to the platen 70 whenever the wheel segment 190 is moved. On the 100 other hand the plate 291 is shifted to present the type character 293 for printing the word "thousand" to the platen 70 whenever the wheel segment 191 or 192 is moved.

In event the amount of the check is less 105 than ten cents, only the wheel segments 193 and 200 will be moved. Under these circumstances it is desirable that a cipher be printed from each of the wheel segments 195 and 201 and a dollar sign printed from the wheel segment 196. That is to say, if the amount of the check is nine cents the printing should be \$0.09. To this end the wheel segments 195 and 201 are each supplied with a type character 298 for printing a cipher and the wheel segment 196 is provided with a type character 299 for printing a dollar sign, all of which are normally presented to the platen 70. 110 115

The dollar sign should be printed from 120 each of the wheel segments 197, 198 and 199 only when the amount of the check is such as to begin with a figure which is printed from the wheel segment next to the left, as viewed in Fig. 5. Similarly a dollar 125 sign should be printed from a position next to the right of the wheel segment 199, as viewed in Fig. 5, when the amount of the check is represented by a number which begins with a figure to be printed from the 130

- wheel segment 199. To this end a type character 300 for printing the dollar sign is movably mounted in each of the wheel segments 197, 198 and 199 and in the movable plate 288. The type character 300 in each of the wheel segments 197, 198 and 199, normally occupies a position in front of this platen 70, but is slidably mounted in the corresponding wheel segment and 5 normally has its printing surface below the printing position. Similarly, the type character 300 of the plate 288 is slidably mounted in the plate and is so located thereon as to be brought to position in front of the 10 platen 70, with the type character 287 which prints the word "dollars," but it is only elevated to printing plane when a figure is to be printed from the wheel segment 199.
- 15 20 For elevating the several type characters 300 to the printing plane, each of the wheel segments 196, 197, 198 and 199 is provided with laterally projecting cam plate 301 which moves beneath the type character 25 300 of the part next to the right, as viewed in Fig. 5, whenever the wheel segment is moved. If the amount of the check is represented by a number beginning with a figure which is to be printed from the wheel 35 segment 196, the type character 300 of the wheel segment 197, will be elevated to the printing plane for printing a dollar sign by the movement of the cam 301 of the wheel segment 196 under said type character 300. Similarly, if the amount of the check begins with a figure to be printed from the wheel segment 199 all of the type characters 300 will be successively elevated to the printing plane, but all of these type 40 characters, except the one carried by the movable plate 288, will subsequently be moved away from a position in front of the platen 70, by the movement of the wheel segments upon which they are respectively mounted.
- 45 50 Under these circumstances, the dollar sign will only be printed from the type character 300 which is mounted on the movable plate 288.
- A cipher should be printed from all of the wheel segments to the left of the wheel segment 199, as viewed in Fig. 5, whenever the amount of the check is a full number of tens of thousands of dollars. On the other hand, and also referring to Fig. 5, when 55 the amount includes a less number of figures a cipher should not be printed from any of the said wheel segments, which are at the right of the wheel segments, from which the initial figure of the number is to be 60 printed, except as already described for amounts less than one dollar. It is accordingly convenient to provide each of the wheel segments 195, 196, 197, 198, 200 and 201 with a type character 302 for printing 65 a cipher which is so positioned as to be

brought in front of the platen 70 by a slight movement of the corresponding wheel segment.

The movement of the several wheel segments 195, 196, 197, 198, 200 and 201 for bringing the cipher type characters 302 to printing position, as also the movement of the plates 290 and 291 for bringing the type characters 292 and 293 to position for printing the words "hundred" and "thousand" 75 may be accomplished by the use of the cams 303 (Fig. 2), one of which is mounted on the wheel segment next to the right of the part to be moved, as viewed in Fig. 5. There is accordingly a cam 303 upon each 80 of the wheel segments 195, 196, 197, 198, 199 and 201 and this cam operates against a lever 304 (Fig. 2). All of the levers 304 are pivotally supported in alinement between a pair of brackets 305, 306 (Fig. 3), which 85 springs from the tie rod 249 (Fig. 2). That end of each lever 304 which is remote from the end engaged by the cam 303, extends beneath the end of the wheel segment, as 200, which is next to the left of the wheel segment upon which the cam is mounted, as viewed in Fig. 5. In order that the movement of any one of the levers 304 may be communicated to those levers which are at the right, as viewed in Fig. 3, five of the 90 levers, counting from the left in this view, are each equipped with a block 307 which extends beneath the next adjacent lever to the right. It therefore follows that upon movement of the wheel segment 199 (Fig. 100 5) its cam 303 engages the lever 304 which is farthest to the left, as viewed in Fig. 3, and this movement is communicated to all of the remaining levers 304 through the blocks 307. The remaining wheel segments 105 195, 196, 197, 198, 200 and 201 are accordingly all moved to bring their type characters 302 to position for printing ciphers. Similar movement of any one of the wheel segments 195, 196, 197, 198 or 201 causes its 110 cam 303 to engage the corresponding lever 304 for moving all of the remaining wheel segments which are at the left as viewed in Fig. 5.

The cams 303 of the wheel segments 190 115 and 191 act upon levers 371 and 372, respectively, (Fig. 3). These levers are pivotally secured against brackets 373 and 374 which spring from the tie rod 249. A link 375 connects the lever 371 with the crank arm 120 294 upon which the plate 290 is mounted. A link 376 connects the lever 372 with the crank arm 295 upon which the plate 291 is mounted. The lever 372 is also provided with a lateral extension 372^a and this extension is engaged by a cam 303^a formed on the hub of the wheel segment 192. The type characters 292 and 293 for printing the words hundred and thousand are accordingly brought to printing position by move- 125 130

ment of the wheel segments 190 and 191, respectively. The type characters 293 for printing the word thousand is also brought to printing position by movement of the 5 wheel segment 192 when this wheel segment is moved without movement of the wheel segment 191.

It is desirable that the plate 288 be moved to bring the type character 287 for printing 10 the word dollars to printing position, immediately upon movement of any one of the wheel segments 188, 189, 190, 191, or 192. For accomplishing this result a bracket arm 377 depends from the crank arm 289 upon 15 which the plate 288 is mounted. At its lower end the bracket arm 377 is turned outwardly, as indicated at 378, and overlies the levers 304 which are acted upon by the cams 303 of the wheel segments 195, 196, 197, 198 20 and 199. Movement of any wheel segment having type characters for printing any amount from and above one dollar accordingly causes the plate 288 to be shifted for bringing the type character 287 to position 25 for printing the word "dollars".

The several described parts of the amount writing mechanism are actuated from the shaft 277. This shaft is in turn driven from the shaft 76. For this purpose gears 308 30 and 309 are fixed upon the ends of the shafts 76 and 277, respectively, and both of these gears mesh with an intermediate gear 310. The gear 310 is rotatably mounted against the side frame 93. The relation of 35 the gears 308 and 309 is such that the shaft 277 makes one revolution at each operation of the machine. The shaft 247 is driven from the shaft 277 during a part of each of its said revolutions. As shown, a gear 40 segment, 311, is fixed upon the shaft 277 and a pinion 312 is fixed upon the shaft 247. This gear segment and pinion mesh, respectively, with rigidly connected speed increasing gears 313 and 314, whereby the shaft 45 247 is turned through the required number of revolutions during a part of a revolution of the shaft 277. In the form of construction shown this required number of revolutions of the shaft 247 is seven. The speed increasing gears 313, 314, are rotatably mounted 50 against the side frame 92. A Geneva stop mechanism is desirably provided for holding the shaft 247 against rotation except when it is to be driven by the gear segment 55 311. To this end the shoe element 315 of such a mechanism is coaxially mounted with and connected to the gears 313, 314. This shoe coacts with a disk segment 316 which is mounted on the shaft 277.

60 After each printing operation those studs 232, 233, which have been depressed by the keys 71 of the key-board 58 are to be restored and the wheel segment 188 to 201 inclusive are to be returned to the position 65 illustrated in Figs. 2 and 5. These opera-

tions are accompanied by a cam 317 on the shaft 277. The mechanism for restoring the studs 232, 233, includes a restoring bar 318 which extends through the wheel segments 188 to 201, inclusive and is hung at its opposite ends upon cranks, as 319, one of which is pivotally secured against each of the side frames 92, 93, but only one of which is shown. This restoring bar is actuated from the cam 317 through a link 320 which extends downwardly from the crank arm 319. A cam roller 321, is mounted upon the lower end of the link 320 and runs upon the rim of the cam 317. A rounded projection 322, formed upon the rim of the cam engages the 70 cam roller 321 at a predetermined time during the revolution of the shaft 277 for lifting the restoring bar 318. At this time, these studs 232, 233, which have been depressed have been alined in front of the bar 75 318 by the driver 240. They are accordingly restored by the lifting of the bar. A guide link 323 extends between the link 320 and the side frame 93 for maintaining the link 320 and its roller 321 in register with the 80 cam 317.

The mechanism for restoring the wheel segments 188 to 201 inclusive, comprises a bar 324 which extends through slotted openings 325 in the rims of all of these segments. 85 This bar is supported at its opposite ends by cranks 326 which swing upon the shaft 207. Motion is communicated from the cam 317 to the bar 324 through a link 327. This link connects the crank 326 with a second crank 100 328. This second crank is pivotally secured against the side frame 93 at 329 (Fig. 2). The crank 328 carries a cam roller 330 and this cam roller runs in a cam groove 331 which is formed in a side face of the cam 105 317. Accidental displacement of any of the wheel segments 188 to 201 from any adjusted position is prevented by the use of spring stops, as 332 (Fig. 2). Each of these spring stops serves for engaging any one of 110 a series of notches 333 formed in the rim of the corresponding wheel segment and yieldingly holds the segment in adjusted position. Each of the spring stops 332 is supported in alinement with the corresponding wheel 115 segment, as by being secured against a bar 334 which extends between and is supported upon the side frames 92, 93.

To permit the oscillation of the platen 70 between the wheel segments 83 of the type 120 writer mechanism and the wheel segments 188 to 201 inclusive of the amount writing mechanism it extends between and is journaled at its opposite ends in a pair of crank arms 335 and 336 (Fig. 6). These cranks 125 are rigidly mounted upon a rock shaft 337 and are moved by the oscillation of the shaft. The rock shaft 337 extends from side to side of the frame of the machine and is journaled at its opposite ends in the side 130

frames 92 and 93. Preferably the spindle, as 338 of the platen 70 extends through the side wall, as 88 of the case 59, at one end and is provided with a knob 339 to permit of the 5 platen being rotated by hand, when desired. Provision is preferably also made for rotating the platen 70 by power. This is conveniently accomplished from a cam 340 (Fig. 13), which is mounted on the shaft 76 adjacent the cam 146.

The oscillation of the rock shaft 337 for moving the platen 70 from side to side, as in printing the name 53, from the wheel segments 83 of the typewriter mechanism, and 15 the amount 54 from the wheel segments 188 to 201 of the amount writing mechanism, is accomplished from the cam 146. The mechanism for communicating motion from this cam to the rock shaft 337, includes a rock 20 arm 341 which swings upon a stud 342, fixed in the side frame 93. The free end of the rock arm 341 carries a cam roller 343 which runs in a cam groove 344 formed in a side face of the cam 146. A link 345 serves for 25 connecting the rock arm 341 with a crank arm 346 of the rock shaft 337.

The mechanism provided for rotating the platen 70 by power serves to turn the platen after the printing of the amount, as 54, upon 30 each check, as 50, 51, in order that the proper part of the check may be presented toward the wheel segments 83 of the typewriter mechanism for receiving the name, as 53. It also serves for rotating the platen 70 35 to advance the strip of checks, as 50, 51, to bring the succeeding check into position for having the amount, as 54, printed at the desired place thereon.

The mechanism for communicating motion from the cam 340 for rotating the platen includes a swinging gear segment 347 which meshes with a pinion 348 mounted upon the spindle of the platen. Preferably a blunt pawl 348 frictionally holds the pinion 348 against rotation upon the platen spindle to permit of the platen being turned independently of the pinion, as when the platen is manually rotated by the use of the knob 339. The gear segment 347 swings 45 upon the rock shaft 337 and is formed with a crank arm 349 which extends below the shaft. A link 350 connects this crank arm with a rock arm 351. The rock arm 351 is pivotally secured against the side frame 93, 50 as by a stud 352 and carries a cam roller 353 which runs against the rim of the cam 340. The cam roller 353 is held in engagement with the cam 340 at all times by means of a spring 354 which connects the rock arm 351 55 with the rock arm 341. An irregular part, as 355, of the cam 340 serves for swinging the gear segment 347 with the crank arms 335 and 336 of the rock shaft 337 to prevent the platen 70 being rotated by the movement 60 of the pinion 348 over the gear segment 347

when the platen is moved from side to side for printing.

It will be understood that the several type characters are conventionally shown in Fig. 5, and that these type characters may take 70 any of the well known forms adapted to score or emboss the paper to afford protection against changes or erasures. In event it is desired to have the type characters also make an inked impression, provision is made 75 for the application of ink to those characters which have been alined in front of the platen 70 in advance of the printing movement of the platen. The means for effecting this application of ink may take any convenient form. For the purpose of illustration two absorbent ink rollers, indicated at 80 357 and 358 are shown. One of these rollers, as 357 serves for inking the type characters of the amount printing mechanism. The 85 other roller, as 358, serves for inking the type characters 95 of the typewriter mechanism. Each of the rollers 357, 358, extends from side to side of the machine in front of the corresponding set of wheel segments. 90 The rollers are conveniently supported at their opposite ends in a pair of links, one of the links of each pair being shown at 359 and 360. A rock arm 361 fixed upon a 95 rock shaft 362 adjacent each side of the machine, but only one of which is shown, carries a link 359, 360 of each pair. The rock shaft 362 extends from side to side of the machine and is journaled in hangers, as 363, which depend from the corresponding side 100 frame, as 93.

Oscillation of the rock shaft 362 at the proper time serves to move the inking rollers 357, 358, over the corresponding type characters. This is conveniently accomplished 105 from the cam plate 317 (Fig. 3). As shown, a crank arm 364 is mounted on the rock shaft 362, adjacent one end of the same. A link 365 (Fig. 2) is connected with the crank arm 364 and carries a cam roller 368 which 110 runs upon the rim of the cam plate 317. The cam plate 317 is provided with an elevated portion 367 and depressed portion 368, suitably positioned thereon for moving the inking rollers 357, 358 over the corresponding 115 type characters when these have been alined for printing by the use of the key boards 56 and 58. A link 369, which is pivotally connected with a link 365 and swings upon the tie rod 249, serves for guidedly 120 supporting the link 365 in alinement with the proper part of the rim of the cam plate 317.

Printing the stub record strip.

In the form of construction shown, a set 125 of number wheels 400 is provided for printing the amount of each check upon a stub record strip, as 52 in figures. The amounts of the several checks are also accumulated 130

upon a set of number wheels 401 and this last mentioned set of number wheels may also be used for printing when desired. These two sets of number wheels are respectively supported in swinging frames 402 and 403 (Fig. 7).

The platen 62, over which the stub record strip turns, is supported by being journaled in a forwardly extended part of the side frame 92 and a similarly formed part 406, of a standard 407, which rises from the floor plate 65, near the mid width of the machine. The swinging frames 402 and 403 are supported in operative relation with the platen 62 by being mounted on a shaft 404 which has its opposite ends fixed in the said extended parts 405, 406, of the side frame 92 and standard 407.

The setting of the number wheels 400 and 401 in accordance with the movements of the wheel segments 195 to 201, inclusive, of the amount writing mechanism is accomplished by forming ratchet teeth as 408, 409 and 410 upon the rims of the said wheel segments. The arrangement of figures upon the type bearing rims 305 of the wheel segments 195 to 201 requires that these wheel segments may be moved through differing amounts for showing the same figures upon the number wheels 400 and 401. Referring to Fig. 5, if the distances between the several figures "1", "2", "3", etc., upon the wheel segments 195, 196, 197, 198, 200 and 201, be regarded as constituting a unit division or space, the number wheels 400 and 401 should be positioned to show ciphers when the wheel segments 195, 196, 197, 198, 200 and 201 have been moved through the distance of half a space from the positions illustrated in Fig. 5. On the other hand, the number wheels 400 and 401, corresponding to the wheel segments 197, 200 and 201, will not be required to show the figure "1" until these wheel segments have been moved through distances equal to one and one half spaces from the position illustrated in Fig. 5. The number wheels 400 and 401, corresponding to the wheel segments 195 and 198, however, will be required to show the figure "1" when these wheel segments have been moved through a distance equal to but one full space from the position illustrated in Fig. 5, and they should continue to show the figure "1" when these wheel segments have been moved through another half space. Similarly, the number wheels 400 and 401 corresponding to the wheel segments 196 and 199 should show the figure "1" when these wheel segments have been moved through a distance equal to a full space from the position indicated in Fig. 5, and each should continue to show the figure "1" until the wheel segment 196 or 199 has been moved through a distance equal to five and one half spaces, the figure "2" being shown on these number

wheels for the first time when the corresponding wheel segments have been turned through a distance equal to six full spaces from the position illustrated in Fig. 5, after which these number wheels should show a different number for each half space of movement. This last is for the reason that the words "twenty," "thirty," "forty" appear close together on the wheel segments 189 and 192.

It follows that the ratchet teeth 408, 409 or 410 of the wheel segments 195 to 201 are to be differently spaced along the rims of the corresponding wheel segments. The ratchet teeth 408 of the wheel segments 197, 200 and 201 may be evenly spaced, but each tooth will effect only a small angular movement in the corresponding number wheels 400 and 401 by operating against a relatively large pinion 427. The ratchet teeth 409 of the wheel segments 195, 198, will show a space 439 between each two adjacent teeth beginning after a definite number of teeth from the bottom, as viewed in Fig. 22. The ratchet teeth 410 of the wheel segments 196 and 199 will be separated by a long space 440 beginning after a definite number of teeth from the bottom, as viewed in Fig. 21. The ratchet teeth 409 and 410 operate against relatively small pinions, as 427.

In the arrangement shown, the number wheels 400 normally stand with the type characters which print ciphers located above the printing position a distance equal to half the spacing of the teeth upon these wheels, as clearly appears in Figs. 7 and 8. Each number wheel 400 must accordingly be turned through a distance equal to half the spacing of its teeth for the first half space of movement of the corresponding wheel segments 195 to 201. Furthermore the next half space of movement of each of the wheel segments 195, 196, 198 and 199, serves to rotate the corresponding number wheel 400 the full distance equal to the spacing of its teeth. This arrangement provides that while the printing upon the check, as 50, for a sum less than ten cents, as nine cents is " * * * * * * * * 09 cents **" and "\$0.09" that upon the stub record strip 52 is simply the figure nine in the cents column.

A set of vertically arranged double faced racks 411, 412, is associated with each set of number wheels 400, 401. These racks are slidably supported in brackets 413, 414, which extend between and are carried by the side frame 92 and the standard 407. The racks 412 are each composed of two relatively movable elements 415, 416 (Fig. 8), but these two elements of each rack are normally locked together, as by means of a latch 417. As shown, the latch 417, is pivotally secured against the side of the element 416 and has an overturned end 418

which normally enters a notch 419 provided in the adjacent edge of the element 415. A notch 420, in the adjacent edge of the element 416 normally registers with the notch 419 for receiving the overturned end 418 of the latch 417 when the two elements 415, 416 are to be freed for independent movement. Motion is communicated from each of the racks 412 to the corresponding one 10 of the racks 411 by the use of a plurality of horizontally arranged shafts 421 (Fig. 7). A pair of pinions 422 and 423 are mounted on each of these shafts. One of each of the pinions 422 is engaged with the teeth of 15 one of the racks 412 and the pinion 423 on the same shaft is engaged with the teeth of the corresponding one of the racks 411. The shafts 421 are supported by having their opposite ends journaled in plates 424, 425, 20 which are secured against and depend from the bracket 414.

A pinion 426 meshes with each of the racks 412 for imparting motion thereto. Each of these pinions derives motion from 25 the corresponding one of the wheel segments 196 to 201 through the pinion 427 or 427^a, and a train of gears 428 and 429. All of pinions 426, 427, 427^a, and the gears 428 and 429 are arranged in a stationary frame 430 30 which is secured against the rear face of the bracket 413 and extends obliquely upward therefrom.

The number wheels 400 and 401 are forced against the platen 62 for printing upon the 35 stub record strip, as 52. This is accomplished by swinging the corresponding frame 402 or 403, upon the shaft 404. To this end each of these frames is provided with a depending crank arm 431, most 40 clearly shown in Fig. 7. A link, as 432, 433, extends rearwardly from each of these crank arms. At their rear ends, these links are connected with crank arms 434 and 435, respectively. The crank arm 434, is mounted 45 upon a rock shaft 436, and swings loosely thereon. The crank arm 435 is fixedly mounted upon a rock shaft 436. The rock shaft 436 is supported near the floor plate 65, as by having one end journaled in the 50 side frame 92 and the other end journaled in a bracket 437 which is applied to the said floor plate near the mid width of the machine.

The movement of the crank arms 434 and 55 435 is derived from a cam 441, shown in Figs. 4, 16, 17 and 18. The cam is mounted for longitudinal adjustment on the shaft 277 and rotates therewith. An elevated part 442 of the cam 441 serves for imparting motion to the crank arm 434. As shown, the 60 crank arm 434 is one arm of a bell crank lever, the other arm, as 443, of which runs upon the rim of the cam 441 in line with its elevated portion 442. Preferably the elevated portion 442 of the cam 441 is of such

length as to engage the arm 443 in any longitudinally adjusted position of the cam.

Motion is imparted to the crank arm 435 from either one or both of two elevated portions 444, 445, of the cam 441. To this end 70 the rock shaft 436 is provided with a crank arm 446 which extends into engagement with the rim of the cam 441. Preferably the position of the crank arm 446 is such that it is engaged with only the elevated portion 444 of the cam 441 in one of the longitudinally adjusted positions of the cam and is engaged with both the elevated portions 444 and 445 in either one of two other longitudinally adjusted positions of the 80 cam.

The swinging movement of the frames 402, 403, toward the platen 62, serves to disengage the wheels 400 and 401 from the corresponding set of rack bars 411, 412. In 85 order that the number wheels 400 may be returned to their initial positions after each printing operation, it is important that these wheels be brought back into engagement with the rack bars 411 before the return movement of the wheel segments 195 to 201. This is accomplished by so forming 90 the elevated portion 442 of the cam 441 that the movement of the number wheels 400 toward the platen 62 is immediately followed by a return movement of the number wheels toward the rack bars 411. On the other hand, in order that the amounts of 95 succeeding checks may be accumulated upon the number wheels 401, it is desirable that 100 these number wheels be held out of engagement with the rack bars 412 until after the return movement of the wheel segments 195 to 201. To this end, the elevated portion 444 of the cam 441 is made of such length 105 as to retain the number wheels 401 in a partially advanced position until after the return movement of the bar 324 (Fig. 2). As shown, the elevated portion 444 of the cam 441 is of such height that while it serves 110 for moving the number wheels 401 out of engagement with the rack bars 412, these number wheels are not thrown against the platen 62 for printing unless the crank arm 446 is also engaged by the elevated portion 115 445 of the cam 441.

In order that the number wheels 401 may be effective for showing the sum of the amounts of succeeding checks, a suitable carrying mechanism is provided. Whenever one of the wheels 401, except the last one to the left, as viewed in Fig. 7, makes a complete revolution, this carrying mechanism serves to advance the next wheel, as viewed in this figure, a distance equal to 120 the spacing of its teeth. As shown, this is accomplished by releasing the latch 417 and thereby disconnecting the two elements 415 and 416 of the rack bar 412 which is associated with the number wheel 401 to be ad- 130

vanced. The carrying mechanism accordingly comprises a disk 447 which has a projecting tooth 448. One of these disks is interposed between each two adjacent number wheels 401 and is fixed against the adjacent number wheel to the right, as viewed in Fig. 7, as by means of a pin 449 (Fig. 8). Whenever one of the number wheels 401 completes a revolution, the projecting tooth 448 of the associated disk 447 operates against a swinging metallic strip 450 to release the latch 417 of the rack bar 412, which is next to the left, as viewed in Fig. 7. The metallic strip 450 is provided in order that release of the latch 417 may occur in any position of the corresponding rack bar 412. One of these metallic strips extends between each two adjacent rack bars 412 and operates against the overturned end 418 of the corresponding latch 417. The metallic strips 450 are supported by being suspended from the bracket 414.

Upon release of any one of the latches 417 the element 415 of the corresponding rack bar 412 is moved upwardly with reference to the element 416 and thereby advances the associated number wheel 401. This relative movement of the elements 415, 416, of the rack bars 412 is conveniently effected by means of an expansion spring 451 (Fig. 8). One of these springs reacts between the higher end of the element 416 of each rack bar 412, and an overturned end portion 452 of the element 415 of the same rack bar. Each element 415 is restored to engagement with the latch 417, as by the contact of a presser foot 453 with a shoulder 454 provided at the lower end of the element. For this purpose the presser foot 453 is formed upon a rock arm 455, and is made wide enough to extend in front of all of the rack bars 412. The rock arm 455 is pivotally supported upon the floor plate 65 and is actuated from a cam 496 (Fig. 4) on the shaft 277. A link 497 is connected with the rock arm 455, and carries a cam roller 498 which runs upon the rim of the cam 496. A spring 499 reacts between the link 497 and the side frame 92 to hold the cam roller 498 against the cam, and the link 497 is guidedly supported by a crank arm 495 which swings upon the rock shaft 436.

The number wheels 401, like the number wheels 400, also normally stand with the type characters which print ciphers located above the printing position a distance equal to half the spacing of the gear teeth upon these wheels. In order that the half spaces of initial movement of the wheel segments 195 to 201, which occur at each operation of the machine, shall not be accumulated in the sum of the amounts of succeeding checks, and in order, further, that the gear teeth of the number wheels 401 may be positioned to mesh with the gear teeth of the

rack bars 412, provision is made for turning those number wheels 401 which have been advanced, backwardly through a half space of movement, upon each return movement of the wheels toward the rack bars. As shown, 70 a swinging pawl 550, controlled by a spring 551, is pivotally secured against the side of the element 415 of each rack bar 412. When the number wheels 401 are disengaged from the rack bars 412, as in Fig. 8, the pawls 75 550 are advanced by their springs 551 to the position illustrated in this figure. Upon the return movement of the number wheels toward the rack bars, each number wheel which has been previously rotated to present a type character to printing position in front of the platen 62, is rotated in the reverse direction through a distance equal to one-half the spacing of its gear teeth, by engagement with the corresponding pawl 80 550. The movement of each pawl 550 is limited by a pin 552, which is fixed in the side of the element 415 of the corresponding rack-bar 412 and is engaged with a slot 553 in the pawl. 90

It will be understood that movement imparted to a number wheel 401 by the carrying mechanism will sometimes be required to extend through a distance equal to one and one-half times the spacing of the gear 95 teeth, and at other times will be required to extend only through a distance equal to the spacing of the gear teeth. This is for the reason that if one of the number wheels 401 is subsequently to be rotated by a corresponding movement of the wheel segment 195, 196, 197, 199 or 201, it should be rotated by the carrying mechanism only through a distance equal to the spacing of its gear teeth. On the other hand, when a number 100 wheel 401 is not to be rotated by a movement of the corresponding one of the said wheel segments, then, if any movement is imparted to it by the carrying mechanism, this movement should be through a distance 105 110 equal to one and one-half times the spacing of its gear teeth. Provision is accordingly made for normally limiting the amount of movement between the elements 415 and 416 of each rack bar 412 to a distance equal to the spacing of the gear teeth on the element 415, while still permitting it to be extended through the greater distance when occasion 115 requires. To this end, the element 416 of each rack bar is provided with a longitudinally extended recess 554 and a lug 555, formed on the element 415, enters this recess. The whole length of the recess 554 is sufficient to permit movement between the elements 415 and 416 through a distance 120 125 equal to one and one half times the spacing of the said gear teeth, but the recess 554 is normally shortened by the extension of a pawl 556 into one end of the same, the pawl 556 being normally engaged by the lug 555 130

to limit the movement between the elements 415 and 416 to a distance which is only equal to the spacing of the said gear teeth. The pawl 556 is pivotally secured against the 5 side of the element 416 of the corresponding rack bar 412 and extends below said element.

When the movement between the elements 415 and 416 is to be through a distance equal to one and one half times the spacing of the 10 gear teeth upon the element 415, the pawl 556 is withdrawn from the recess 554. This is conveniently accomplished from the cam 496 (Fig. 4). As shown, a movable bar 557, extends transversely over the floor plate 65 adjacent the projecting lower ends of the 15 pawls 556. A forward movement of this bar, after the movements of wheel segments 195 to 201 have been completed, serves to swing the pawls 556 of each and all of the 20 rack bars 412 which have not been elevated by a movement of the corresponding wheel segment. It follows that if the carrying mechanism has already operated to raise the element 415 of any rack bar 412 through a 25 distance equal to the spacing of the gear teeth on said element, and the rack bar has not been subsequently elevated by a movement of the corresponding wheel segment 195 to 201 the spring 451 will now serve to 30 raise the element 415 through an additional distance equal to one half the spacing of the said gear teeth.

The bar 557 is slidingly held against the floor plate 65 by screws 558 which extend 35 through slots in said bar and the bar is normally retracted by a spring 559. An arm 560, formed on the link 497 (Fig. 19) extends downwardly to a position in rear of the bar 557, whereby the bar is advanced by 40 a forward movement of the link. For imparting this forward movement to the link 497, the cam 496 (Fig. 4) is provided with an elevated portion 561.

The clearing of the number wheels 401 45 may be accomplished from the cam 441. As shown, a series of frictionally driven clearing pinions 456 are provided. These pinions are supported in position to mesh with the number wheels 401 when their use is required. For this purpose they are mounted 50 upon a spindle 457 and this spindle is supported between a pair of swinging arms 458, 462. The pinions are spaced along the spindle with a friction disk 459 splined upon 55 the spindle between each two adjacent pinions. For obtaining a frictional engagement between the disks and pinions, a spring 460 is coiled about the spindle 457 and reacts between a collar 461, fixed upon the spindle 60 near one end, and the adjacent disk 459. The swinging arm 462 is pivotally secured against the side frame 92 at 463 (Fig. 4). The swinging arm 458 is pivotally supported in alinement with the arm 462, as upon the 65 higher end of a standard 464 which rises

from the floor plate 65. The arm 458 is continued beyond the standard 464 and carries a cam roller 465 for coöperating with an elevated portion 466 of the cam 441 in one of the longitudinally adjusted positions 70 of the cam. The engagement of the cam roller 465 with the elevated portion 466 of the cam swings the arms 458, 462, to bring the clearing pinions 456 into mesh with the number wheels 401. 75

For rotating the clearing pinions 456 a gear pinion 467 is fixed upon the spindle 457 at the remote side of the arm 458 from the collar 461. This gear pinion is in constant mesh with a gear segment 468. The 80 gear segment 468 is formed upon the end of a swinging arm 469 and this arm is pivotally mounted upon the standard 464 in alinement with the pivotal support for the arm 458. A spring 470 (Fig. 15) reacts between the 85 arm 458 and a downwardly projecting portion 471 of the arm 469 for normally holding the arm 469 against a stop pin 472 fixed in the arm 458.

The gear pinion 467 is rotated for driving 90 the clearing pinions 456 by swinging the arm 469 away from the stop pin 472. For this purpose a bell crank lever 473 is provided. This bell crank lever is pivotally supported upon the crank shaft 436 and has 95 one arm 477 engaged with the downwardly projecting portion 471 of the arm 469. The other arm 478 of the bell crank lever 473 is engaged with the rim of the cam 441. A spring 474 reacts between the arm 477 of 100 the bell crank lever 473 and the arm 458 for holding the arm 478 of the bell crank lever in engagement with the cam and normally retaining the clearing pinions 456 in elevated position out of mesh with the number wheels 401. Movement of the arm 469 away from the stop pin 472 for spinning the clearing pinions 456 is accomplished by the engagement of a projecting part 475 of 105 the cam 441 with the arm 478 of the bell crank lever 473. Preferably the projecting part 475 is so positioned upon the cam as to engage the arm 478 in only that one of the longitudinally adjusted positions of the cam wherein the elevated portion 466 is alined 110 with the cam roller 465. A shallow notch 476 is provided between two adjacent teeth of each of the number wheels 401 to prevent the turning of these wheels by clearing pinions 456 when they have been brought to the 115 position illustrated in Figs. 7 and 8. As each of the number wheels 401 reaches this position, the rotation of the corresponding clearing pinion 456 is interrupted by the engagement of one of its gear teeth with the shallow 120 notch 476 of the number wheel but further rotation of the spindle 457 is permitted by reason of the frictional engagement between the pinions 456 and disks 459. Preferably 125 the relative positions of the projection 475 130

and elevated portion 466 of the cam 441 are such that the clearing pinions 456 have been elevated out of engagement with the number wheels 401 during the return movement 5 of the arm 469 toward the stop pin 472.

Showing a visible total.

In order that the sum of the succeeding checks may be observed at any time, as 10 through the sight opening 60 (Figs. 1 and 19), an additional set of total wheels 480 is supported within the chamber of the case below the opening. If desired provision may be made for turning each of these total 15 wheels to accord with the positions assumed by the wheels 401. The total wheels 480 are rotatably mounted in alinement upon a common spindle 481. For simplicity of illustration but one of the wheels 480 is shown. The spindle 481 is mounted at the top of a frame 482. This frame is secured against and extends above and below the bracket 414. Each total wheel 480 preferably has a gear pinion 483 formed upon its 20 hub. The gear pinion 483 meshes with a short rack 484 which is formed upon the higher end of a vertically movable plunger 485. This plunger is slidingly held against the frame 482, as by means of cleats 486, 25 487. It is preferably spring elevated, the spring 488 being attached to the cleat 486.

Gear pinions 489, uniform as to the number of teeth with the number wheels 401 and all of like construction, are in constant mesh 30 with the said number wheels. These gear pinions 489 are mounted in alinement upon a spindle 490. This spindle extends between the side members of the frame 403 below the number wheels 401. Each pinion 489 35 has a stepped snail plate 491 fixed against one of its side faces, the number of steps, as 492, upon the rim of each snail plate being equal to the number of teeth provided in each number wheel 401. Each plunger 485 has a forwardly turned hooked lower 40 end 493 for engagement with the rim of one of the snail plates 491. The elevation at which each plunger is held by its spring 488 is accordingly determined by the angular position of the corresponding number 45 wheel 401. The set of total wheels 480 are thereby actuated to show the same number which is presented toward the platen 62 by the number wheels 401.

50 Inasmuch as all of those number wheels 401 which have been rotated at all are turned backwardly through a distance equal to half the spacing of their gear teeth at each return movement of the wheels toward the 55 rack-bars 412, it follows that each of such wheels must be again turned forwardly at least through an equal distance before the movement toward the platen 62 is repeated. Furthermore this must occur as to each of 60 such wheels even though the wheels may not

be again rotated by a movement of the corresponding wheel segment 195 to 201, or by the operation of the carrying mechanism.

For rotating these number wheels 401, which are to be positioned for printing, 70 when they are not turned, either by a movement of the corresponding wheel segment 195 to 201 or by an operation of the carrying mechanism, I provide the arrangement of parts which is most clearly illustrated in 75 Fig. 19. These parts include a series of pawls 562. The pawls 562 are equal in number to the number of rack-bars 412, or number wheels 401, but only one of them is shown. The pawls depend from a transverse pivot rod 463, carried by the bracket 414 in rear of the rack bars 412. They are provided with overlapping blocks 564, similar to the blocks 307 formed upon the levers 304, the block 564 provided upon each pawl 80 85 562 extending in rear of the next pawl to the right, as viewed from the front end of the machine. These pawls provide that a forward movement of any one of the pawls imparts a corresponding movement to all 90 of the remaining pawls upon its right-hand side, as viewed in the said direction. The lower end 565 of each pawl 562 extends into a position alongside of the corresponding rack bar 412 and adjacent a depending arm 95 566 of the associated latch 417. Intermediate its ends, each pawl 562 is provided with a depending prong 567. This prong has an oblique cam face 568 at its lower end.

An actuating arm 569, having a beveled 100 upper edge, extends transversely beneath, but normally out of alinement with, the depending prongs 567 of the pawls 562. The actuating arm 569 conveniently constitutes the upper horizontal member of an upright 105 rectangular open frame 570. The frame 570 extends about the set of pinions 426. The side members, as 571, of the frame are slidingly held against the bracket 413, as by cleats, one of which is shown at 473. The 110 frame is elevated by the forward movement of the link 497. For this purpose, a cam lug 572 is formed on the link 497. This cam lug operates against the lower end of a link 574, which is connected with the frame 115 570. For guidedly supporting the link 574 and maintaining its lower end in register with the cam 572, a fixed stud 575 extends inwardly from the side wall 88 and enters a slot 576 formed in the link. Owing to 120 the width of the frame 570 provision is preferably made for insuring that its opposite ends will have the same movement. As shown, the two ends of the frame are connected to a common rock shaft 226, as by 125 links, one of which appears at 227. The rock shaft 226 extends transversely in front of the rack bars 412, and is journaled in lugs, as 228, formed on the bracket 413.

The positioning of the pawls 562 for lo- 130

cating the prongs 567 above the actuating arm 562 is conveniently determined by the movable plungers 485 of the mechanism for showing a visible total. As shown, each 5 plunger 485 is provided with a cam depression 577, and a pin 578 projects laterally from the adjacent pawl 562 and enters this depression when the plungers are positioned as in Fig. 19. Each plunger 485 occupied 10 the position illustrated in Fig. 19 when the corresponding number wheel 401 is so disposed as to present a cipher toward the platen 62. Furthermore, the steps, as 492, of the snail plates 491, are each of such 15 width that the turning of the number wheels 401 through distances less than the spacing of their gear teeth does not change the position of the corresponding plunger 485. On the other hand, a movement of any one of 20 the number wheels 401, through a sufficient distance to enable it to present a figure toward the platen 62 serves to lower the corresponding plunger 485. This movement of the plunger advances the associated pawl 25 562 by a cam action to bring its prong 567 into alinement with the actuating arm 569. Furthermore, the overlapping blocks 564 will cause the pawls which are associated with the remaining number wheels 401 to 30 the right, as viewed in Fig. 7, to be similarly advanced. This advancing of additional pawls by the overlapping blocks 564 is required for the reason that if a figure is 35 printed in any column, as for example, the hundreds column, the remaining number wheels to the right should be rotated to printing position, even though they are to print only ciphers, and if arranged to print ciphers the corresponding plungers 485 will 40 not have been lowered to advance the associated pawl 562.

Upon the upward movement of the actuating arm 569, those pawls 562 which have been advanced to bring their prongs 567 45 into alinement with the arm, are thrown against the depending arms 566 of the latches 417 by the cam engagement of the beveled edge of the actuating arm with the oblique cam face 568 of the prong. This 50 operation serves to swing the corresponding latches 417, to a position in which the overturned end 418 of each latch registers with an elongated recess 579 provided in the element 415 of the corresponding rack bar 412. 55 This recess extends downwardly from the corresponding notch 419. The spring 451 is thereby permitted to raise the element 415 for rotating the corresponding number wheel 401 through a distance equal to half 60 the spacing of its gear teeth. Any number wheel which has previously been rotated, and all number wheels to the right of such number wheel, as viewed in Fig. 7, are accordingly brought to position to present a 65 cipher or figure directly toward the platen

62, even though these number wheels may not have been rotated, either by a movement of the corresponding wheel segment 195 to 201, or by the carrying mechanism during the current operation of the machine. 70

The arrangement provides for the printing of amounts involving the use of less than the whole number of number wheels 401 without printing ciphers at the left of the initial figure of the amount. In bringing this about the number wheels 401 normally occupy a position in which the character for printing a cipher is elevated above the printing position a distance equal to half the spacing of the gear teeth upon these 80 wheels. The rotation of each number wheel 401 through the half space movement necessary to bring one of its type characters to printing position is accomplished by either one of three means viz:—(1) by a rotation 85 of the corresponding wheel segments 195 to 201, (2) by the operation of the carrying mechanism, or (3) by the movement of the corresponding pawl 562, while the accomplishment of such movement by any one 90 of the three said means precludes its being accomplished by either one of the other two, during the same operation of the machine. It will be understood that the arrangement by which the printing of ciphers at the left 95 of the total is avoided when the printing involves the use of less than the whole number of number wheels 401, does not prevent a display of ciphers at the left of the amount of the total, as shown at the sight opening 100 60 under the same circumstances.

When the amount of the last total includes a less number of figures than the whole number of number wheels 401, these 105 number wheels will require to have their gear teeth alined before they can be engaged by the clearing pinions 456. This is provided for by so positioning the elevated portion 466 (Fig. 15) on the cam 441 that the clearing wheels 456 are not lowered until the rack bars 412 have been restored by the operation of the cam 317 (Fig. 3.) The 110 pawls 550 normally project so far in front of the rack bars 412 (Fig. 8) as to become engaged with the gear teeth of the number 115 wheels 401 upon the restoration of the rack bars and effect a sufficient alinement of these gear teeth to enable them to be entered by the gear teeth of the clearing pinions 456. During the rotation of the number 120 wheels 401 by the clearing pinions 456, each pawl 550 yields against the effort of its spring 551 to permit it to be passed by the gear teeth of the corresponding number 125 wheel.

Controlling the operation.

The power driven parts of the machine are preferably at rest during each use of the key boards 56 and 58. The spring pawl 130

78 of the clutch arm 77 (Fig. 11) is therefore normally held out of the path of the studs 79, as by the contact of a stop shoulder 500 with a crank arm 501 formed on the pawl. The stop shoulder 500 is conveniently formed on a crank arm 502 of a rock shaft 503. This rock shaft 503 extends between and has its opposite ends journaled in the side frames 92, 93.

10 The crank arm 502 is moved for withdrawing the stop shoulder 500 from engagement with the crank arm 501, by the depression of any one of three spring elevated plunger keys, marked 504, 505 and 506 (Fig. 1). These plunger keys are exposed upon the top of the case 59 in front of the key board 52. Each slides through the cover panel 61 and through a cleat 507 (Fig. 2) secured against the front wall 64 upon the inside. The stem of each of the keys 504, 505 and 506 is rearwardly offset adjacent its lower end, as at 510 (Fig. 2) and the offset portion is provided with a wing cam 508 having a forwardly and downwardly facing oblique side. Upon the depression of the corresponding key this wing cam 508 acts against a movable rod 509 (Fig. 4). The rod 509 is carried by crank arms 510, one at each end of the 30 rod. Each of these crank arms swings from the floor plate 65 as by being journaled in a cleat, 511, which is fixed upon the said floor plate. Movement of the rod 509 is communicated to the crank arm 502 and serves to withdraw the stop shoulder 500 from engagement with the crank arm 501 of the spring pawl 78 (Fig. 11). For this purpose, a link 512 extends between one of the crank arms 510 and a crank arm 40 513 which is mounted on the rock shaft 503.

When the machine is set in motion by the use of the plunger key, 504, the machine operates without longitudinal movement of the cam 441 from its normal position of 45 adjustment, as shown in Fig. 4. In this position of the parts, the elevated portions 444, 446 and 475 are inoperative. No printing is accordingly done from the number wheels 401, nor is there any operation of the clearing pinions 456. The plunger key 504 may therefore be termed the "printing" key. This name is accordingly indicated upon the head of the key, as by marking the same with the letter "P" as appears in 55 Fig. 1.

The plunger keys 505 and 506 both operate against the movable rod 509 in the same manner as does the key 504, but the depression of either these last mentioned keys 60 also serves to longitudinally shift the cam 441. However, depression of the key 505 serves to shift the cam 441 only through a sufficient distance to bring its elevated portion 445 into alignment with the crank arm 65 446 of the rock shaft 436 and without bring-

ing the elevated portions 466 and 475 of the cam into operative positions. Depression of the key 506, on the other hand, operates to shift the cam 441, through a sufficient distance to render all of its elevated 70 portions operative against the corresponding movable parts. It follows that when the operative parts are set in motion by depression of the plunger key 505, printing is accomplished from the number wheels 401, 75 but the clearing pinions 456 are not operated while, when the operative parts of the machine are set in motion by use of the plunger key 506, printing is accomplished from the number wheels 501 and the clearing 80 pinions 456 are also operated. The plunger keys 505 and 506 may therefore be termed "sub-total" and "total" keys, respectively. These names are accordingly indicated upon the heads of the corresponding 85 keys, as by marking the head of the key 505 with the letter "S" and the head of the key 506 with the letter "T" as appears in Fig. 1.

The required shifting of the cam 441, upon depression of the keys 505 and 506, 90 is accomplished by providing the offset lower end portions of these keys with wing cams 514 and 515 of different widths. Each of these wing cams operates against a projecting stud 516 or 517 (Fig. 4) of a crank 95 arm 518 or 519. These crank arms swing in a transverse direction with reference to the length of the machine. Each crank arm 518, 519, has a pivotal support in a cleat 520, secured against the floor plate 65, and 100 the two crank arms are connected by a link 521. The link 521 is in turn pivotally connected with one end of a horizontally swinging shipper lever 522. This shipper lever is pivotally supported intermediate its 105 ends, as upon a post 523 which rises from the floor plate 65. A spring 524 reacts between the shipper lever 522 and a fixed stud 525, secured in the floor plate 65, to normally hold the shipper lever at the limit 110 of its movement in one direction.

In order that movement of the shipper lever 522 may serve to shift the cam 441, a fork 526 is formed upon that end of the shipper lever which is remote from the 115 link 521 and this fork is engaged with an annular groove 527 formed in the hub, as 528, of the cam. The cam 441 is also provided with a pair of annular grooves 529 and 530. A fixed stud 533 enters one or 120 the other of these last mentioned grooves to hold the cam in the corresponding position of longitudinal adjustment during one complete revolution.

To permit the entrance of the fixed stud 125 533 into each groove 529, 530, the cam 441 is notched, as indicated at 531 and 532, Fig. 16, the notches providing openings into the grooves. At the completion of each revolution of the cam 441, the parts of the machine 130

are brought to rest by the engagement of the crank arm 501 of the spring pawl 78 with the stop shoulder 500. At this time the fixed stud 533 registers with the notches 531 and 532 and if movement of the cam 441 has been accomplished by a longitudinal shifting of the same, the cam is returned to the position illustrated in Figs. 4 and 16, by the spring 524. The fixed stud 533 may 5 be supported in the required position in any 10 convenient manner. As shown, it is formed upon a bracket plate 534 which is secured against the floor plate 65.

15 *Correcting errors in the amount to be written.*

In order that the amount to be written upon the check, as 50, at each operation of the machine, may be shown upon the key 20 board 58, provision is desirably made for holding down the keys 71 which have been used. To this end, the stems 217 of all the keys 71 of each row or set, extend through openings, as 535, in a sliding plate 536 (Fig. 23). Preferably there are as many of these sliding plates as there are rows or sets, as 25 208 to 216 inclusive, of keys and a separate plate is associated with the keys of each row or set, (Fig. 3).

30 The stem 217 of each key 71 is provided with two oppositely facing pairs of notches 537, 538 and 539, 540. The notches 537 and 538 of one pair each have an upwardly facing shoulder 541 and a downwardly facing 35 oblique cam wall 542. The lower notch 537 is deeper than the upper notch 538 for a reason to be hereinafter explained. Similarly the notches 539 and 540 of the other pair each have a downwardly facing abrupt 40 shoulder 543, and an upwardly facing oblique wall 544.

The plates 536 are supported for longitudinal sliding movement below the cover panel 61, as by being mounted upon studs 45 545, one of which is secured against the under side of the cover panel adjacent each end of the corresponding plate, and passes through a slotted opening 546 in the plate 536, but only one of which studs is shown. 50 Leaf springs 547 each secured against one of the studs 545 and reacting upon the corresponding plate 536, serve for moving the plates in a forward direction and resisting their rearward movement. When a key 71 55 is depressed, in any row, the inclined wall 542 of the notch 537 in its stem 217 serves to retract the corresponding plate 536 against the effort of its spring 547, until the upwardly facing shoulder 541 of the 60 notch 538 passes below the plate. The spring 547 then serves to advance the plate 536 and the elevation of the key 71 by its spring 355 is prevented by the engagement of the plate with the notch 538. Inasmuch

as the notch 539 is shallower than the notch 65 537, the plate 536 is not advanced to its original position and the depression of other keys 71 in the same row is prevented by the engagement of the plate 536 with the downwardly facing abrupt shoulders 543 of the 70 notches 539, on said other keys.

When an examination of the depressed keys 71 shows that the desired amount will be printed upon the check, as 50, the machine is ready for operation and one of the 75 plunger keys 504, 505, or 506 will be depressed. Preferably, the depression of any one of these plunger keys serves to permit the restoration of all of the keys 71, which have been depressed, as by their respective 80 springs 355. To this end, provision is made for imparting a rearward movement to each of the sliding plates 536 upon the depression of any one of the plunger keys 504, 505 or 506. As shown, a movable restoring bar 85 548 extends transversely beneath the cover panel 61 in front of the forward ends of the sliding plates 536. This restoring bar is carried by cranks, as 549, which swing upon pivots, as 579, formed on the plate 218. A 90 rod 580, extends transversely between the crank arms 549 and normally rests in notches, as 581, one of which is formed in the stem of each of the plunger keys 504, 505 and 506. Each notch 581 has an oblique 95 wall 582. Depression of any one of said plunger keys accordingly serves to advance the rod 580, by a cam action, and throw the restoring bar 548 against the forward ends of the sliding plates 536. The stems 217 100 of the depressed keys 71 are thereby released from the plate 536 and these keys are elevated by their springs 355. Elevating springs, as 583, are preferably also provided for the plunger keys 504, 505, and 506. 105 As most clearly shown in Fig. 2, each of these springs has one end connected with the stem of the corresponding plunger key and the other end secured against the under side of the plate 218.

110 Should an examination of the key board 58 at any time show that a key 71 has been improperly depressed in any of the rows 208 to 216 inclusive, it is important that the improperly depressed key may be restored and the depression of another key in the same row permitted, without the restoration of keys which may have been depressed in any of the remaining rows. Such a restoration of any improperly depressed key 115 120 also requires the restoration of the corresponding depressed stud 232 or 233 in the wheel segments 188 to 194. As shown a blank or restoring key 225 is associated with each row 208 to 216 inclusive of keys in the 125 key board 58, for this purpose.

The stem 584 of each blank key 225 slides through the cover panel 61, through the

- plate 218 and through the corresponding sliding plate 536. Below the plate 218 the stem 584 of each blank key 225 is turned rearwardly as indicated at 585 (Fig. 23).
- 5 At the place where each stem 584 passes through the corresponding sliding plate 536, it is notched and the notch has a downwardly facing oblique cam wall 586. Upon the depression of any blank key 225 the corresponding plate 536 is accordingly retracted by a cam action and any depressed key 71 in the row with which the blank key is associated is released. Preferably each blank key 225 is provided with an elevating spring 587 similar to the elevating spring 355 provided for each of the keys 71. No provision is made for retaining the blank keys 225 in depressed position and each of such keys is restored immediately after its depression.
- For restoring an improperly depressed stud 232 or 233 the rearwardly extended lower end portion 585 of the stem 584 of each blank key 225 engages with and depression 25 presses a lever 588 upon the depression of the blank key. One of the levers 588 is pivotally mounted upon each of the wheel segments 188 to 194 inclusive. These levers are supported in the path of the rearwardly extended lower end portions 585 of the stems of the blank keys 225 when the said wheel segments occupy the positions illustrated in Fig. 2. In the case of the wheel segments, as 30 188 to 192 inclusive, which have separated side plates 203, 204, the levers 588 are pivotally supported between the plates. In the case of the wheel segments 193 and 194, wherein the body portion of the segment is composed of a single plate or disk 206, the 35 corresponding levers 588 are pivotally secured against the side of the disk 206, the levers 588 of the two wheel segments being located upon opposite sides of the disks.
- The rear end portion of each lever 588 operates against a restoring bar 589 or 590. The restoring bars 589 are associated with the wheel segments 193 and 194. Each bar is slidably mounted against the side face of the corresponding plate or disk 206 over the 40 end of the associated lever 588. The studs 233 of the wheel segments 193 and 194 accordingly have laterally overhanging heads 591 providing shoulders against which the corresponding restoring plate 589 may react for elevating the studs. The restoring bars 590 are associated with the wheel segments 188 to 192. Each of these last mentioned bars is located between the side plates 203 and 204 of the corresponding wheel segment. 45
- 60 The studs 232 of the wheel segments 188 and 192 are therefore each provided with an intermediate depending lug 592 against which the restoring plate 590 may react for elevating an improperly depressed stud.

A pawl arm 593, similar to that employed 65 upon typewriters for rotating the platen roll, is supplied for turning the platen 62. Any convenient means may be employed for swinging the pawl arm 593 at each operation of the machine. As shown the pawl 70 arm is connected with the swinging frame 492 by a link 594. The printing upon the platen 62 is desirably accomplished through an inked ribbon indicated at 595 (Fig. 19). This ribbon is similar to those now in common use upon typewriters and may be supported in a similar manner (not shown).

I claim as my invention,—

1. In combination, a plurality of separately movable type carriers, types mounted 80 on all of the carriers constructed to print different parts of the word name of any number comprising a number of figures equal to the number of the said type carriers, a set of keys controlling the movement of each type 85 carrier and an additional set of keys each operable to control the movement of two of the type carriers.

2. In a check writing machine, in combination, two platens, three separately movable sets of type, the types of one set being constructed to print numbers in words and the types of the other two sets being constructed to print numbers in figures, the word printing type and one set of the figure 95 printing type coöperating with one of the said platens, the type of the remaining set coöperating with the other platen, and unitary means for moving types of all of the sets whereby all of the sets of type are arranged to print the same number.

3. In a check writing machine, in combination, two platens, a set of type constructed to print numbers in words, three sets of type each constructed to print numbers in 100 figures, the types of the first mentioned set and of one of the other sets coöperating with one of the said platens and the types of the two remaining sets coöperating with the other platen and unitary means for moving 110 the first mentioned set of type and two of the remaining sets of type including the set which coöperates with the same platen with the said first mentioned set whereby all three of the said sets of type are arranged to print 115 the same number, and totaling mechanism communicating motion from one of the said three sets of type to the remaining set of type.

4. In a machine for writing checks, in 120 combination, a rotatable roll platen over which the check turns, name printing and amount printing type coöperating with the platen from different angular positions separated by a circumferential distance on the 125 platen greater than the distance between the places for the impressions of the said two types on the check, and actuating means caus-

ing a coaction of the platen with the said two types in succession and a rotation of the platen for advancing the check over the platen between its coactions with the said two types.

5. In combination, a plurality of separately movable type carriers, types mounted on all of the carriers constructed to print different parts of the word names of any number comprising a number of figures equal to the number of said type carriers, an equal number of separately movable figure type carriers, means for moving the first mentioned type carriers to aline the types mounted thereon for printing the word name of any selected one of the said numbers and coupling means communicating motion from each of the first-mentioned type carriers to one of the said figure type carriers.
- 10 6. In combination, two equal sets of separately movable type carriers, a plurality of types mounted on each of the carriers of both sets, means operable successively upon the carriers of one set to move said carriers for alining selected types mounted thereon, a single coupling member operable between each of the last mentioned carriers during its movements and one of the carriers of the other set and means for shifting the coupling member between its said operations.
- 15 7. In combination, a plurality of separately movable sets of types, the types of all of the sets being constructed to print different parts of the word name of any number comprising a number of figures equal to the number of sets of types, means for moving the sets of types for arranging the types to print the word name of a selected one of the said numbers and accumulating means operated by the movement of the sets of types for showing the sum of the numbers which the types are arranged to print by a plurality of operations of the said moving means.
- 20 8. In combination, a pair of coöperating separately movable sets of type characters, the type characters of one set comprising the full word name of each of the two figure numbers ten and the multiple of ten and a part only of the word name of each of the numbers eleven to nineteen inclusive and the type characters of the other set comprising the full word name of each of the unit numbers and the remaining part of the word name of each of the unit numbers and the remaining part of the word name of each of the numbers eleven to nineteen inclusive.
- 25 9. In combination, a plurality of sets of movable types, the types of all of the sets being constructed to print different parts of the word name of any number comprising a number of figures equal to the number of sets of types, means for moving the types to print a selected number and accumulating means operated by the movement of the types for showing the sum of the numbers
- which the types are arranged to print by a plurality of operations of the said moving means.
10. In combination, two pairs of coöperating separately movable sets of type characters, the type characters of one set comprising the full word name of each of the two figure numbers ten and the multiples of ten and a part only of the word name of each of the numbers eleven to nineteen inclusive, the type characters of the other set of the same pair comprising the full word name of each of the unit numbers and the remaining part of the word name of each of the numbers eleven to nineteen inclusive, the type characters of one set of the other pair comprising two sets of the digits and the type characters of the remaining set comprising a set of the digits with the first digit repeated for each of the numbers eleven to nineteen inclusive, means for moving the sets of type characters of one pair to aline selected type characters of the two sets in said pair and coupling means communicating motion from each set of type characters of the last mentioned pair to one of the sets of type characters of the other pair.
- 15 11. In a machine for writing checks connected together in strip form, in combination, a rotatable roll platen over which the strip of checks turns, name printing and amount printing type coöperating with the platen from different angular positions, and actuating means successively causing a coaction of the platen with the said two types and a rotation of the platen for advancing the strip of checks over the platen.
- 20 12. In a machine for writing checks connected together in strip form, in combination, a rotatable roll platen over which the strip of checks turns, name printing and amount printing type coöperating with the platen from different angular positions separated by a circumferential distance on the platen greater than the distance between the places for the impressions of the said two types on the same check, and actuating means causing a coaction of the platen with the said two types in succession and rotations of the platen for advancing the strip of checks over the platen between and following its coactions with the said two types.
- 25 13. In a machine for writing checks connected together in strip form, in combination, a rotatable roll platen over which the strip of checks turns, a pair of sets of separately movable carriers, a set of type mounted upon each carrier, selecting mechanism operable upon the carriers of each set for moving them to aline selected types upon the two sets of carriers in front of the platen from different angular positions, and actuating means successively causing a relative printing movement between the platen and

the two sets of alined types and a rotation of the platen for advancing the strip of checks over the platen.

14. In a machine for writing checks, in combination, a rotatable roll platen over which the check turns, a pair of sets of separately movable carriers, a set of type mounted upon each carrier, selecting mechanism operable upon the carriers of each set for moving them to aline selected type upon the two sets of carriers in front of the platen from different angular positions separated by a circumferential distance on the platen greater than the distance between the places for the impressions of the two sets of alined types on the check, and actuating means causing a coaction of the platen with the said two sets of alined types in succession and a rotation of the platen for advancing the check over the platen between its coactions with the said two sets of alined type.

15. In combination, two pairs of coöperating separately movable sets of type characters, the type characters of one set comprising the full word name of each of the two figure numbers ten and the multiples of ten and a part only of the word name of each of the numbers eleven to nineteen inclusive, the type characters of the other set of the same pair comprising the full word name of each of the unit numbers and the remaining part of the word name of each of the numbers eleven to nineteen inclusive, the type characters of one set of the other pair comprising two sets of the digits and the type characters of the remaining set comprising a set of the digits with the first digit repeated for each of the numbers eleven to nineteen inclusive, actuating mechanism operable upon the two sets of type characters of the first described pair for moving them to aline selected type characters for printing the word name of any two figure numbers and coupling mechanism for transmitting movement from each of the last mentioned sets of type characters to one of the sets of type characters of the other pair.

16. In combination, a pair of separately movable type carriers, an actuating arm, a set of movable studs mounted on each type carrier, and each stud being movable into and out of the path of the actuating arm, and a set of keys having bifurcated stems with the two parts of the stems of each key operable simultaneously upon studs of different type carriers.

17. In combination, two sets of type, a set of movable studs determining the selection of type from each set and a set of keys each operable simultaneously upon a stud of both sets.

18. In combination, a plurality of sets of number type, a set of movable studs determining the selection of type from each set,

a plurality of sets of keys equal in number to the number of sets of type and a key of each set being operable upon a stud of one set and an additional set of keys each operable simultaneously upon a stud of two adjacent sets.

19. In combination, a pair of separately movable sets of type, the types of one set being constructed to print a part only of the word names of the numbers eleven to nineteen inclusive and the types of the other set being constructed to print the remaining parts of the word names of said numbers and a set of nine keys each operable to determine the selection of type from both sets.

20. In combination, a pair of separately movable sets of type, the types of one set being constructed to print the full word names of the two figure numbers ten and the multiples of ten and a part only of the word names of the numbers eleven to nineteen inclusive and the types of the other set being constructed to print the full word name of each of the unit numbers and the remaining part of the word name of each of the numbers eleven to nineteen inclusive and three sets of nine keys, the keys of two sets being each operable to determine the selection of type from one of the said sets and the keys of the remaining set being each operable to determine the selection of type from both of the said sets.

21. In combination, a plurality of coaxially mounted rotatable type carrying wheel segments, a cam fixed to each wheel segment, a plurality of levers each engaging one of the cams for being moved thereby upon rotation of the wheel segment to which the cam is fixed and acting upon the next adjacent wheel segment for rotating the same and a series of leaves each fixed upon one of the levers and overlapping the next adjacent lever.

22. In combination, a plurality of separately movable carriers arranged side by side, a set of type mounted upon each carrier, an oscillating actuating member shiftable between each of its oscillations, a set of movable studs mounted in each carrier said studs being normally out of the path of travel of the actuating member and means for selectively moving a stud of each set into the path of travel of the actuating member, the actuating member being successively positioned for operation against the studs of the several carriers by its said shifting movements.

23. In combination, two sets of separately movable type carriers, the carriers of each set being arranged side by side, an oscillating actuating member shiftable between each of its oscillations and operable to move a type carrier of one set by its oscillation, and successively engaging the different type carriers of said set by its shifting and a single

shiftable coupling member successively connecting the type carriers of the other set with the type carriers of the first separately mentioned set during their respective periods of engagement by the actuating member.

24. In combination, a movable carrier, a set of figure type mounted on the carrier to be successively brought to a common 10 printing position by the movement of the carrier and one of the figures being repeated in the set, an accumulator, a gear wheel through which the accumulator is operated and a mutilated gear movable with the carrier and engageable with the first named gear wheel for driving the same, the omission of teeth in the said mutilated gear being in accordance with the repetition of figures in the said set of type.
25. In combination, two relatively movable series of characters, the characters of one series comprising the full word name of each of the two figure numbers ten and the multiples of ten and a part only of the word 20 name of each of the numbers eleven to nineteen inclusive, the characters last mentioned being arranged in order in the series and preceding the character twenty and the characters of the other series comprising the full 25 word name of each of the unit numbers and the remaining part of the word name of each of the numbers eleven to nineteen inclusive, the characters last mentioned alternating in the said other series with the unit 30 characters.

26. In combination, two series of separately movable type carriers, the carriers of each series being arranged side by side, means for moving the carriers of one series 40 in succession, and a single shiftable coupling member successively connecting the type carriers of the other set with the type carriers of the first separately mentioned set during their respective periods of movement.

27. In combination, two equal sets of separately movable type carriers arranged side by side, the carriers of one set being of different widths and the carriers of the 50 other set being of uniform width, means operable successively upon the carriers of one set to move said carriers for alining selected types mounted thereon, and a single coupling member having uniform shifting 55 movements alternating with the movements of the said operating means and operable thereby to connect each of the last mentioned type carriers during its movement with one of the type carriers of the other set.

28. In combination, two equal sets of separately movable type carriers arranged side by side, the carriers of one set being of different widths and the carriers of the other set being of uniform width, means operable 65 successively upon the carriers of one set

to move said carriers for alining selected types mounted thereon, a coupling member having uniform shifting movements alternating with the movements of the said operating means, a single stud mounted on the coupling member for engagement successively with the type carriers of uniform width in order from one end of the set upon repeated shifting movements of the coupling member and additional studs mounted on 75 the coupling member for engagement successively with the type carriers of different widths during the engagements of the first mentioned stud with the type carriers of the other set. 80

29. In combination, a plurality of separately movable type carriers of different widths arranged side by side, and an oscillating actuating member having uniform shifting movements alternating with its oscillations operable to move a type carrier by its oscillation and successively engaging the different type carriers by its shifting. 85

30. In combination, a set of separately movable type carriers of different widths arranged side by side, an oscillating actuating member having uniform shifting movements alternating with its oscillations and a set of studs mounted upon the actuating member and located along the same for engagement 90 successively with the several type carriers in order from one end of the set upon repeated shifting movements of the actuating member. 95

31. In combination, two equal sets of separately movable type carriers, the carriers of each set being arranged in a row which is transverse to the direction of their movement, a plurality of types mounted on each of the carriers of both sets, an oscillating 100 driving member, an oscillatable coupling member, means for laterally shifting the driving member after each of its complete oscillating movements and before the beginning of its next oscillating movement for 105 successively engaging it with the type carriers of one set during its movements in one direction, means for laterally shifting the coupling member after each of its movements in one direction and before its corresponding return movement, the coupling member thereby connecting each of the type carriers of the last mentioned set during its engagement by the driving member with the corresponding type carrier of the other 115 set and means for effecting the said return movements of the coupling member. 120

32. In combination, two equal sets of separately movable type carriers, a plurality of types mounted on each of the carriers of both sets, a single shiftable driving member 125 separately operable in its different positions upon the carriers of one set to move said carriers for alining selected types mounted thereon, and means for transmitting move- 130

ment from each of the type carriers of the last mentioned set to the corresponding type carrier of the other set.

33. In combination, a set of separately movable type carriers, types mounted on all of the said carriers constructed to print different parts of the word name of any number comprising a number of figures equal to the number of said type carriers, an equal set of figure type carriers, means for moving the type carriers of one of the said sets to aline the types mounted thereon for printing any selected one of the said numbers, and means for transmitting movement from each of the type carriers of the last mentioned set to the corresponding type carrier of the other set.

34. In combination, a set of separately movable type carriers, types mounted on all of the said carriers constructed to print different parts of the word name of any number comprising a number of figures equal to the number of said type carriers, an equal set of figure type carriers, and means for moving the type carriers of both sets for printing the same number being any selected one of the first mentioned numbers.

35. In combination, two groups of type each comprising a like number of sets of movable types, the types of all of the sets in one group being constructed to print different parts of the word name of any number comprising a number of figures equal to the number of sets of type in the said group, the type in the other group being figure type, and means for selecting type from

both groups for printing the same number being any selected one of the first mentioned numbers.

36. In combination, two groups of type each comprising a like number of sets of movable types, the types of all of the sets in one group being constructed to print different parts of the word name of any number comprising a number of figures equal to the number of sets of type in the said group, the type in the other group being figure type, means for selecting type from both groups for printing the same number being any selected one of the first mentioned numbers, and accumulating means operated by the said selection of type for showing the sum of the numbers which the types are selected to print by a plurality of operations of the said selecting means.

37. In combination, a plurality of sets of movable types, the types of the several sets being constructed to print different parts of the word names of a plurality of different numbers, means for moving the types for arranging them to print the word name of any selected one of the said numbers, and accumulating means operated by the movement of the types for showing the sum of the numbers which the types are arranged to print by a plurality of operations of the said moving means.

Correction in Letters Patent No. 1,248,096

It is hereby certified that in Letters Patent No. 1,248,096, granted November 27, 1917, upon the application of William J. Fabian, of Evanston, Illinois; for an improvement in "Check-Writing Machines," an error appears in the printed specification requiring correction as follows: Page 22, lines 54-55, claim 8, strike out the words "the unit numbers and the remaining part of the word name of each of"; and that the said Letters Patent should be read with this correction therein that the same may conform to the record of the case in the Patent Office.

Signed and sealed this 4th day of June, A. D., 1918.

[SEAL.]

F. W. H. CLAY,

Acting Commissioner of Patents.
